UNITED STATES PATENT OFFICE.

GEORGE R. MARTIN, OF EAST ORANGE, NEW JERSEY, ASSIGNEE TO WESTERN ELECTRIC COMPANY, INCORPORATED, OF NEW YORK, N. Y., A CORPORATION OF NEW YORK.

TELEPHONE SYSTEM.

Application filed March 18, 1926. Serial No. 95,563.

This invention relates to telephone exchange systems and more particularly to systems employing automatic apparatus for establishing connections.

5 The invention is in the nature of an improvement on the system shown in Patent No. 1,573,412, issued to H. W. MacDougall and A. S. Bertels Feb. 16, 1926, and it is the object of the present invention to provide an improved testing system of the type disclosed in that application for testing selector switch units.

10 A feature of the invention is the provision of means for indicating the identity of the selector under test.

15 A further feature of the invention lies in the provision of means for periodically checking the accuracy of the above mentioned identifying means.

20 An additional feature of the invention lies in the provision of improved means for synchronizing a plurality of switches.

25 A still further feature of the invention lies in the provision of means for the non-sequential use of testing selectors.

30 To give an idea of the appearance of these features in the operation of the present embodiment of the invention, a brief outline of the operation will be presented. A routine test is started with all the apparatus at rest. The operation of the start key advances a pair of directing selectors one step. These selectors are synchronized by a special arrangement and control the remainder of 35 the test circuit. One of a number of sequence switch type selectors or connectors is then positioned to associate the test circuit with the district selector or the office selector which is used as a test selector.

40 These connectors are so arranged that the test selectors may be used in any order. If the test selector is busy the test circuit waits until it becomes idle at which time it is made busy to service connections. At this 45 time a register or locating selector is positioned under the control of the directing selector to determine the first incoming selector to be tested. The test selector is now directed, without advancing its associated 50 sequence switch off-normal, to the first in-

coming selector in the group where the test is to be started. The incoming selector is then operated to select one of a group of final selectors having access to the final multiple test line and the selected final selector is positioned on that test line. The control relays of the incoming selector are tested by the test circuit after which the final multiple test line tests the ringing operation. The test circuit and the test line cooperate to test the supervisory relay of the incoming selector after which the incoming selector is released. The test selector and the locating selector are each advanced one step and the tests are repeated on the next incoming selector. The incoming selectors are separated into groups by means of overflow lines and circuits are completed with both the locating selector and the test selector in the overflow position which cooperate to 55 advance these selectors to the next incoming selector. Lamps are also provided under the control of the locating selector and a key which identify the incoming selector under test. Any number of selectors may be 60 grouped together for the purpose of the test. When the test of such a group is completed, the test selector is returned to normal and the directing selectors advanced one step. In this position the connector switches, and 65 locating selector are reset to test the next group. To begin a test at a particular incoming selector groups of keys are provided which arbitrarily position the directing 70 selectors and the locating selector in position to test the desired incoming selector. Other keys control the setting of an incoming selector in a position other than that 75 leading to the final multiple test line.

80 Referring to the accompanying drawings, Fig. 1 shows a district selector used as a test selector. Calling subscribers' lines are normally extended to the district selector by means of the line finder shown therein and the operation of the switch is normally directed by sequence switch 100. When used 85 as a test selector, it is directly connected to the testing controlling circuit at the contacts of the connector switches of the test apparatus and the selector is controlled from 90 95 100

the test apparatus to associate an incoming selector switch therewith.

Fig. 2 shows an incoming selector switch and its auxiliary circuit. This is a typical incoming selector of the type to be tested by this testing system.

Fig. 3 illustrates a final selector switch used in conjunction with this test to connect the incoming selector switch to a test line located on the final frame.

Fig. 4 shows a test line used alone for testing certain functions of the incoming selector switch and in conjunction with the test apparatus for testing other functions of said switch.

Fig. 5 shows keys to control the selection of a particular incoming selector for test together with a key for returning the test circuit to normal.

Fig. 6 shows connector switches 600 and 650. These connectors are of the sequence switch type and are controlled in such a manner that particular selector switches are removed from service and associated with the testing control circuit in a non-sequential order.

Fig. 7 illustrates apparatus and circuits to control the positioning of the test selector.

Figs. 8 and 11 illustrate a group of switches or directing selectors acting in the nature of registers. These directing selectors are operated in pairs, switches 800 and 1100 operating together and switches 810 and 1110 cooperating with each other. The terminals served by each brush are connected to a terminal rack which is cross-connected to other terminal strips and thence to the desired apparatus. The cross-connections are shown only as used and reference is made to the above identified patent to MacDougall and Bertels for a typical arrangement of similar cross-connections.

Fig. 9 shows a pair of locating selectors which control the selection of the group of switches to be tested and in cooperation with the lamps indicate the selector under test.

Fig. 10 illustrates apparatus and circuits for controlling the incoming selector switch to be tested. This control circuit is designed to direct the incoming selector switch to a final selector switch which is in turn directed to a final multiple test line.

Fig. 12 illustrates a compound timing device operated in such a manner that switch 1210 is progressively positioned to count a predetermined period of time for the testing control circuit to seize and test a selector switch and start the test of an incoming selector switch. Switch 1200 is operated to time the period during which the incoming selector switch is under test. The time period allotted for the operation of switches 1200 and 1210 is adjusted so that should the various operations not be completed with-

in such period, an alarm is sounded to indicate the fact to an attendant.

Figs. 13 and 14 show auxiliary apparatus for assisting in the testing of the incoming selector.

Fig. 15 is a diagram showing the order in which the sheets of the drawing should be arranged.

Description of apparatus.

Key 601 of Fig. 6 is a start key; the operation of key 558 returns the test apparatus completely to normal; keys 556, 500 and 501, together with key sets 510, 520 and 530, control the selection of a particular selector for test; keys 1302 and 1304, together with key sets 1050 and 1060, control special tests, key 1039 is operated to repeat a test on an incoming selector and key 1038 used to advance the test sequence switch when trouble is encountered.

The key sets 510, 530 as well as keys 500 and 501 of Fig. 5 are electrically released after connection has been made with the particular selector. Key set 520 is released by the operation of the return to normal key.

The directing selectors of Figs. 8 and 11, the locating selectors of Fig. 9 and the timing switches of Fig. 12 are all switches of the step-by-step type. In order that the two switches constituting the directing selector shall be in synchronism, special means has been provided for advancing the switches from normal from terminal 21 and also for moving them rapidly to a particular terminal. Briefly the operation is as follows:

The operating circuits for the magnets of the switches extend through the bank of the switch. A second circuit is provided for the magnet of the first switch through a relay. This relay is prevented from operating by the circuit through the terminal bank. Spare positions are cross-connected to ground through relay 749 and all terminals are grounded by the operation of key 553. Hence in passing spare terminals or in moving to a particular terminal by the operation of key 556, the operating circuit is maintained until the desired terminal is reached from which ground is removed by the operation of a key of set 510. When the ungrounded terminal is reached the shunt is open and the above mentioned relay operates to supply battery to the magnet of the second switch to advance it to the corresponding terminal which is also ungrounded.

As above mentioned switches 800 and 1100 make up one directing selector and switches 810 and 1110 make up the second directing selector. As many directing selectors together with the relays associated therewith may be provided as are necessary. The cor-

responding brushes of all directing selectors are cross-connected to the same racks. Therefore, in order to simplify the drawings the corresponding switches of the directing selectors have been grouped together and for the same reason separate terminal racks have been shown with the contacts thereof multiplied together. The first arc of each switch is used for positioning the switch itself. 5 Arcs 802 and 812 in cooperation with the locating selectors mark the last incoming selector in the group for the purpose of resetting the directing selector. Arcs 803 and 813, 10 805 and 815, 806 and 816 control the amount 15 of resistance used in the fundamental circuit at various times. Arcs 804 and 814 vary the capacity between the fundamental circuit and ground. Key 809 may be used to remove this capacity. Arcs 1103 and 1113 control 20 the positioning of the locating selectors of Fig. 9. Arcs 1104 and 1114 are cross-connected to operate relay 1225 or relay 1443 when necessary. Relay 1225 transfers the fundamental circuit from relay 1224 to relay 25 1228 for incoming selectors employing 24 volt transmission. Relay 1443 is used to alter the test when a three wire incoming selector is being tested. Arcs 1105 and 1115 are cross-connected to alter the operation 30 where the district selector switch is reached through a line switch and where the final multiple test line does not supply the synchronizing pulses as described later. Arcs 1106 and 1116 control the selection of the 35 district selector which is to be used as a test selector. As will be pointed out in greater detail later, the wiring of the sequence switch type connector switches permits the use of the test selectors in any order under the control of these arcs of the directing selectors. This renders changes in the test circuit to care for changes in the grouping of the incoming selectors much easier than in the arrangement of the above identified Mac-Dougall-Bertels patent. 45

The locating selectors have a plurality of functions. They serve to control district group selection; they serve to indicate the number of incoming selectors in the panel bank; they also cooperate with the test selector to insure that the indication is correct. The locating selectors are positioned under the control of the directing selector to correspond with the number of the first incoming selector in the group to be tested. The 50 arc served by brush 903 of the tens locating selector completes the counting relay circuits for determining the group of incoming selectors to be tested. 55

The incoming selector is identified by the frame in which its terminals appear, by the brush which has access to said terminals and by its individual position among the 100 terminals to which each brush has access. Each district selector brush serves 100 sets

of terminals which are divided into 8 groups of ten sets each and two groups of five sets, each group being followed by a set called an overflow set. The first set of the groups will bear the following numbers; 0, 11, 22, 33, 44, 55, 66, 77, 88 and 94. The overflow terminals will bear the numbers; 10, 21, 32, 43, 54, 65, 76, 87, 93 and 99. The locating selectors are positioned by grounding corresponding terminals of brushes 906 and 916 through the directing selector. The group beginning with No. 94 is arrived at by grounding the No. 9 terminal in the tens locating selector and after that switch has been brought to rest transmitting the ground to the No. 4 terminal in the units locating selector. The units locating selector is advanced one terminal each time that the district selector is advanced one terminal. It is advanced automatically over its Nos. 11 and 22 terminals in order to retain the decimal relation between the switches, and at the same time the tens locating is advanced one terminal. At the overflow positions circuits are closed through brushes 902 and 912 which cooperate with a circuit controlled by the overflow position of the district selector to advance the test. The failure of the locating selectors and the district selector to reach overflow position at the same time blocks the progress of the test. Brushes 901 and 911 operate certain relays to indicate that the test of the group has been completed. 95

If an incoming selector fails to operate correctly and its identity is desired in order to make adjustments therein, key 956 will be operated. This key supplies battery to lamp set 940 and thence through a contact closed by the connector sequence switch to ground identifying the district selector being used as a test selector, and therefore, the frame on which the incoming selector appears. It also operates relays 951 and 957 to transfer the lead which has been used in brush selection to one of the set of lamps 960 identifying the brush of the district selector. In addition it will supply battery for indicating the number of the incoming selector. 110

The operation of the timing arrangement of Fig. 12 will be clear from the detailed description to be given later. 115

General description. 120

An automatic routine test of incoming selector switches is started by the actuation of key 601. The operation of this key brings about the movement of the first directing selector to its first position. With the directing selector positioned ground is connected to one of the contacts cross-connected to brush 1106 to position one of the connector sequence switches in position to test the district selector which is to be used as a test 125 130

selector. This selector is then tested for busy condition and is seized for use. When ready for use, sequence switch 700 is advanced and the locating selectors are positioned. District brush and group selections are made, leaving the test selector on the terminals leading to the first incoming selector of the group. This selector is tested for busy condition and when it becomes idle is controlled to select one of a group of final selectors. This final selector is then positioned on the final multiple test line. The test line applies certain tests after which the test apparatus and the test line cooperate to test the supervisory relay of the incoming selector. The incoming selector is then restored to normal as well as the final selector. The units locating selectors and the test selector are then advanced one terminal and the second incoming selector tested. Where the group of selectors to be tested in one position of the directing selector is greater than that between overflow terminals, a circuit is provided for checking the overflow position and advancing the district selector. When the end of a group is reached, the district selector is restored to normal and that selector reset or other selectors positioned, together with the locating selectors, to start the test in the new group.

Detailed description.

In order to start a routine test of all the incoming selectors in an office, start key 601 will be operated. The operation of key 601 closes a circuit for relay 701, provided all the connector sequence switches, such as 600 and 650, are normal, which circuit may be traced from battery, through the winding of relay 701, lower left contact of cam 602, upper contact of cam 651, contact 603 of start key 601 to ground. A holding circuit for relay 701 is closed before this energizing circuit is opened and maintained as long as any one of the connector sequence switches is off-normal and key 601 is operated. This circuit extends from the winding of relay 701 over the lower right contact of cam 602, or over the lower left contact of cam 602 and the lower right contact of cam 651, to the front contact of relay 701 and ground at contact 613 of key 601.

The operation of relay 701 closes a circuit for advancing the first pair of directing selectors 800 and 1100 to their first off-normal terminals. This is accomplished by means of a circuit from ground over the outer right contact of relay 701, conductor 708, right back contact of relay 550, serially through the normal terminals of key set 520 to the normal terminals of brushes 801 and 1101. This circuit is extended through brush 801, back contact and winding of stepping magnet 807 to battery, stepping switch 800 to its first off-normal position and opening the cir-

cuit of magnet 807. The operation of relay 701 closes a second circuit from battery through the winding of stepping magnet 807 and its back contact, through the winding of relay 850, right back contact of relay 1150, right back contact of relay 1151, conductor 1152, lower contacts of cam 702, to ground at the inner right contact of relay 701. As long as switch 800 remains in its normal position, the winding of relay 850 is shunted by the ground connected to the normal terminal of brush 801. The advance of switch 800 to its first off-normal position opens this shunt and permits the operation of relay 850.

Relay 850 in operating completes a circuit from battery over its front contact through the winding of stepping magnet 1107 of directing selector 1100, back contact of that magnet, brush 1101 and its normal terminal, to ground at the right front contact of relay 701 as above traced. Magnet 1107 now operates and advances directing selector 1100 to its first off-normal terminals.

When magnet 1107 recloses its back contact a circuit is completed from battery over the front contact of relay 850, winding and back contact of magnet 1107, left back contact of relay 1150, inner left back contact of relay 1151, winding of relay 1154, conductor 1155, lower right contact of cam 702 to ground at the inner right contact of relay 701. The operation of relay 1154 closes an obvious circuit for relay 1153 which locks to ground over conductor 1172 and contact 613 of start key 601. A second locking circuit is also closed from conductor 1172, front contact of relay 701, conductor 754 to ground at the inner left contact of relay 1153. This circuit also serves to hold relay 701 operated when the start key 601 is restored, until the connector sequence switches are returned to normal. With all connector sequence switches normal the circuit of relay 701 is opened and that relay releases, opening the locking circuit of relay 1153 and releasing the latter relay.

Relay 1153 in operating closes a circuit from battery through the winding of relay 551, conductor 553, to ground at the outer left front contact of relay 1153. The operation of relay 551 connects ground from the back contact of relay 552, outer right front contact of relay 551, conductor 554, lower contacts of cam 703, conductor 709, to brush 1106 of directing selector 1100. The terminals of brush 1106 are connected to a cross-connecting block from which they are cross-wired to another cross-connecting block. The terminals on this second connecting block control the positioning of the connector sequence switches 600 and 650. Assuming the cross-connections to be as shown, the circuit may be further traced over conductor 1157, upper right contact of cam 653, winding of sequence switch magnet 650

to battery. Sequence switch 650 is moved from position 1 to position 2 in this circuit. It is then moved from position 2 to position 4 in a circuit from battery through the winding of the sequence switch magnet, upper left contact of cam 652, lower right contact of cam 605, upper right contact of cam 652 to ground. In position 4 of connector sequence switch 650 the district selector which is to be employed as a test selector is tested to find whether or not it is busy.

The district selectors which may be used as test selectors are of three types. One type is that adapted to be selected by means of a line switch individual to the calling line. A district selector of this type may be found in U. S. Patent 1,395,977 to F. A. Stearn et al., granted November 1, 1921. A second type of district selector is directly associated with the line finder and sender selector. A district selector of this type may be found in U. S. Patent No. 1,541,356 to F. S. Irvine, granted June 9, 1925. A third type of district selector is controlled by a link circuit and is also directly associated with a line finder. A district selector of this type is disclosed in U. S. Patent No. 1,567,072 granted to W. H. Matthies, December 29, 1925. The district selector which has been shown in full and is associated with the first operative position of sequence switch 600 is of the link type. A selector of this type normally stands with its sequence switch in position 2 and is associated with a link circuit prepared to serve an incoming call.

With sequence switch 650 in position 4 a circuit is closed from battery through the winding of relay 654, back contact of relay 655, back contact of relay 656, right contact of cam 657, and thence over conductor 1157 through the cross-connecting blocks to brush 1106 and to ground as previously traced. The operation of relay 654 closes a circuit from ground over its left front contact through resistance 704 and lamp 705 to battery. Lamp 705 indicates that the district selector is being tested for busy condition and remains lighted until the district selector is ready for use as a test selector. It also closes a circuit from ground through the winding of relay 658, over the inner right front contact of relay 654, right contact of cam 659, conductor 660, lower left contact of cam 101, winding of sequence switch magnet 100 to battery advancing sequence switch 100 to position 3. The operation of relay 658 closes a circuit from ground over its front contact, left contact of cam 661, conductor 662, to the link circuit. This ground causes the link circuit to advance to find a sender and then to put the district selector circuit through a simulated wipe out call without moving the selector off-normal.

Relay 655 is connected through cam 671 to the automatic test set for district selectors

in such a manner as to be operated if the district test set is testing the district selector to be used as a connecting selector. The operation of relay 655 lights lamp 705 and opens the circuit of relay 654, preventing the above operations until the test of the district has been completed.

When sequence switch 100 reaches position 1 following this wipe out call or following a service call, a circuit will be closed from ground through the windings of relay 663, winding of relay 664, outer right front contact of relay 654, lower left contact of cam 665, conductor 666, contact 103 of jack 104, lower contact of cam 105, resistance 106 to battery. If no link circuit is testing the district at this time, relay 663 will operate and close a shunt around its high resistance winding, from ground at its front contact, over the lower contacts of cam 706, to its right winding. Relay 664, which is marginal, now operates and closes a circuit from battery, through the left winding of relay 667 to ground at the front contact of relay 664. Relay 667 in operating disconnects conductor 666 from the link circuit, and connects ground through resistance 668 over the upper contact of cam 669 to conductor 670, preventing the link circuits from taking this selector for use in a service connection.

The operation of relay 664 when sequence switch 100 reaches position 1, following a service connection, prevents the establishment of the above traced circuit for relay 658 and the advance of the district selector sequence switch from position 1.

In addition, the operation of relay 667 closes a circuit from battery through the winding of relay 656, innermost right front contact of relay 667, lower contacts of cam 651, left front contact of relay 701 to ground at contact 613 of key 601. Relay 656 in operating opens the circuit of relay 654 and that relay releases extinguishing lamp 705. Relay 656 also closes a holding ground for relay 667 which may be traced over the front contact of relay 656, right contact of cam 657, conductor 1157, through the cross-connecting racks associated with brush 1106 in its first off-normal position, conductor 709, lower contacts of cam 703, conductor 554, outer left front contact of relay 551, to ground at the back contact of relay 552. The release of relay 654 disconnects relays 663 and 664 from conductor 666. The operation of relay 667 previously described also extends its operating ground over its left front contact, upper right and lower left contacts of cam 707, conductor 1158, front contact of relay 1154, conductor 607, to the right winding of relay 606 and battery. Relay 606 operates in this circuit and closes a circuit from battery through the sequence switch magnet 700, lower left contact of cam 710, outer right front contact of relay

606, contact 603 of start key 601 to ground, in which sequence switch 700 advances to position 2.

When sequence switch 700 leaves position 5 1 1/4, the operating circuit of relay 606 is opened and that relay releases, advancing sequence switch 700 to position 3 in a circuit through the winding of the magnet, lower right contact of cam 710, outer right back contact of relay 606 to ground over contact 608 of start key 601.

With the sequence switch 700 in position 3 a circuit is closed from ground over the upper left contact of cam 720, lower right contact of cam 652, lower right contact of cam 605, upper left contact of cam 653, winding of connector sequence switch magnet 650 to battery, advancing the connector switch to position 5.

In position 5 the conductors extending from the test circuit and from the district selector are connected together. Relay 667 is held operated at this time over its middle right front contact, lower contacts of cam 651, front contact of relay 701 to ground at contact 613 of the start key 601. The continued operation of relay 667 serves to hold the district selector busy and prevent its use in a service connection.

With sequence switch 700 in position 3 a circuit is closed from battery through the winding of relay 711, upper left contact of cam 712, windings of relay 713, upper contacts of cam 715, conductor 716, back contact of relay 1422, conductor 1424, left contacts of cam 717 to ground. Relay 711 in operating closes a holding circuit over its outer left front contact, to the upper left contact of cam 712, and thence over the circuit as previously traced to ground. It also closes a circuit from battery through the winding of sequence switch magnet 700, conductor 718, inner left front contact of relay 1154, conductor 1159, upper left contact of cam 719, inner left front contact of relay 711, upper left and lower right contacts of cam 717 to ground. Sequence switch 700 is advanced to position 4 in this circuit.

The advance of sequence switch 700 to position 4 serves to test whether the directing selectors have been properly positioned. When sequence switch 700 left position 1, the original energizing circuit for relay 1154 was opened by the deenergization of relay 850. If the directing selectors are occupying the same position, battery is supplied for relay 1154 through the winding of magnet 807, back contact of that magnet, No. 1 terminals of brushes 801 and 1101 which are strapped together, left back contact of relay 1150, inner left back contact of relay 1151, to the winding of relay 1154 and relay 1154 remains energized. With relay 1154 operated the above traced circuit for advancing

sequence switch 700 to position 4 is completed.

With sequence switch 700 in position 4 a circuit is closed from battery through the winding of up-drive magnet 107 of the district selector, conductor 672, lower contact 50 of cam 673, lower contact of cam 719, inner left front contact of relay 711, upper right and lower left contacts of cam 717 to ground. The completion of this circuit causes the advance of the district selection in a brush selecting movement. At the same time, commutator strip 108 is connected to the winding of relay 711, and a circuit which may be traced from battery through the winding and outer left front contact of relay 711, right contacts of cam 721, lower contact of cam 675, conductor 674, commutator strip 108, brush 111, right contact of cam 110, to ground is completed each time that brush 111 encounters a conducting segment on strip 108. The completion of this circuit shunts relay 713 and permits it to release.

When sequence switch 700 reached position 4, with relay 713 operated, a circuit was closed from ground over the front contact of relay 713, left contact of cam 722, conductor 723 to brush 1102. Assuming that the first terminal of brush 1102 is cross-connected as shown, this circuit may further be traced over contact 1160, innermost back contact of relay 950, conductor 951, Figs. 9 and 14, winding of No. 0 counting relay 1421, conductor 1014, upper left contact of cam 1001 to battery. Relay 1421 operates in this circuit and closes a locking circuit 95 for itself through the windings of relays 1422 and 1423 in parallel to ground at the front contact of relay 1421. The presence of ground on conductor 951 prevents the operation of these relays. However, when relay 713 is shunted by the brush selecting commutator 108 and releases, ground is removed from conductor 951 and relays 1422 and 1423 operate.

The operation of relay 1422 opens the circuit of relays 713 and 711 and these relays release. The release of relay 711 opens the circuit of the up-drive magnet 107 and brings the district selector to rest in position to select the first brush set. With relay 711 deenergized and relay 1422 operated, a circuit is closed from battery through the winding of sequence switch magnet 700, upper right contact of cam 710, right back contact of relay 711, conductor 724, front contact of relay 1422, conductor 1424, left contacts of cam 717 to ground. Sequence switch 700 advances to position 5 in this circuit.

With sequence switch 700 in positions 5 and 6 a circuit is closed from battery through the winding of district selector trip magnet 109, conductor 676, lower contact of cam 677, lower right contact of cam 726 to

ground. The operation of the trip magnet 109 performs the usual function of tripping the brush set at the beginning of group selection.

With sequence switch 700 in position 5, the previously traced circuit for relays 711 and 713 is again closed and these relays operate. The operation of relay 711 will advance sequence switch 700 to position 6 provided the locating selectors 900 and 910 have been positioned.

The positioning of these locating selectors is under control of the arc of directing selector 1100 served on brush 1103. As soon as sequence switch 700 reaches position 2, a circuit is closed from battery through the windings of stepping magnet 907 of locating selector 900, back contact of relay 908, contact of interrupter 909, upper left contact of cam 725 to ground. A second circuit is also closed from battery through the winding of magnet 917 of locating selector 910, back contact of relay 918, contact of interrupter 919, lower right contact of cam 725 to ground. However, a circuit is closed as soon as the directing selector 1100 is positioned, from ground over the lower left contact of cam 725, through the normal contacts of the keys of brush set 530 to brush 1103, over the cross connecting racks associated therewith, to terminals of brushes 906 and 916 in the locating selectors. These brushes are connected through the windings of relays 908 and 918, respectively, to battery. Therefore, when the locating selectors have been advanced by the operation of magnets 907 and 917, to the terminals grounded by the directing selector, these relays will operate and open the circuits of the stepping magnets bringing the switches to rest in the position desired.

As pointed out elsewhere, the arrangement of the incoming selectors in the terminal banks of district selectors is such as to make the numbers of the first terminal set of the various groups as follows: 0, 11, 22, 33, 44, 55, 66, 77, 88, and 94. It is therefore clear that to position the locating selectors to control the selection of the first incoming selector of a group, corresponding terminals on the arcs served by brushes 906 and 916 must be grounded except in the case of the last group. In this case the grounding of the No. 9 terminals of brush 906 causes the operation of relay 908 in the usual manner. The operation of relay 908 extends the ground which operated relay 908 over the outer right contact of that relay to the No. 4 terminals of brush 916 to operate relay 918.

With the first terminal of brush 1103 cross-connected as shown, relays 908 and 918 will be operated when brushes 906 and 916 engage their No. 0 terminals on which they may or may not be standing at the begin-

ning of the test. The circuit of relays 908 and 918 is maintained until switch 700 leaves position 6 so that these relays are operated with switch 700 in position 5 and a circuit is closed from battery through the winding of sequence switch magnet 700 over conductors 718 and 1002, inner right contact of relay 908, left front contact of relay 918, conductor 952, right contact of cam 719, inner left front contact of relay 711, upper right and lower left contacts of cam 717 to ground, advancing sequence switch 700 to position 6.

With sequence switch 700 in position 6, the up-drive magnet 107 is reoperated and a circuit is also closed from ground over the right contact of cam 110, brush 112, commutator strip 113, conductor 678, cam 679, left contacts of cam 712 to the contact of relay 711. This circuit serves to shunt the winding of relay 713 each time that brush 112 engages a conducting segment of commutator strip 113. Relay 713 in operating closes a circuit from ground over its front contact, lower right contact of cam 722, conductor 727, brush 903 and its No. 0 terminal, conductor 951, winding of relay 1421, conductor 1014, upper left contact of cam 1001 to battery. The No. 0 counting relay 1421 operates and closes the previously traced locking circuit for itself. As before, when the first conducting segment of the commutator strip is encountered, relay 713 releases and opens the energizing circuit of relay 1421 and permits the operation of relays 1422 and 1423 in the locking circuit of relay 1421.

With sequence switch 700 in position 6 commutator strips 108 and 114 are connected together at cam 721, strip 108 being connected over conductor 674, lower contact of cam 675 to the lower right contact of cam 721; strip 114 being connected over conductor 680, lower contact of cam 681, to the lower left contact of cam 721. When relay 1423 operates as above described, this circuit is extended over the upper left contact of cam 721, conductor 728, front contact of relay 1423, conductor 1425, to the front contact of relay 711, so that relay 711 is maintained energized until the brush set of the district selector is centered on the first terminals of the desired group. This arrangement is particularly of value when two-wire office selectors are employed as test selectors. When the brush set is centered, relay 711 releases. With relay 1422 operated a circuit is closed from battery through the winding of sequence switch magnet 700, upper right contact of cam 710, right back contact of relay 711, conductor 724, front contact of relay 1422, conductor 1424, left contacts of cam 717 to ground, advancing sequence switch 700 to position 7.

When sequence switch 700 reached posi-

tion 2 $\frac{3}{4}$, a circuit was closed from battery through the left winding of relay 729, upper right contact of cam 730 to ground.

When sequence switch 700 reaches position 6 $\frac{1}{2}$, this operating circuit is opened, but a second circuit extending from sleeve brush 115 serves to hold that relay operated provided the incoming selector to be tested is busy. This circuit may be traced from ground to the terminal engaged by brush 115, conductor 682, lower contact of cam 683, conductor 684, contact 555 of key 556, conductor 557, right front contact of relay 729, contact 760 of key 731 and key 751, in shunt of the winding of relay 738, right winding of relay 729, lower right contact of cam 732 to battery. Relay 729 remains operated as long as the incoming selector remains busy. A circuit is also closed from battery over the lower right contact of cam 732, through lamp 733, resistance 734, upper right and lower left contacts of cam 1005, inner left front contact of relay 729, outer left back contact of relay 735, upper right contact of cam 720 to ground, lamp 733 indicating to the attendant that the selector to be tested is busy. When relay 729 releases upon the incoming selector becoming idle, it connects ground to sleeve brush 115 for making the incoming selector busy to service connections. This may be traced from brush 115, over conductor 682, lower contact of cam 683, conductor 684, contact 555 of key 556, conductor 557, right back contact of relay 729, inner left back contact of relay 735, right contact of cam 736 to ground. Relay 729 also closes a circuit for relay 1220 extending from battery over the upper left contact of cam 732, conductor 737, winding of relay 1220, conductor 1221, left back contact of relay 729, outer left back contact of relay 735, upper right contact of cam 720 to ground. Relay 1220 operates and extends the tip and ring conductors through to the test sequence switch establishing a circuit for the usual trunk guard test. This circuit may be traced from battery through the winding of relay 203, lower right contact of cam 202, upper left contact of cam 201, tip conductor 213, district selector brush 116, conductor 685, lower contact of cam 686, conductor 687, outer left front contact of relay 1220, conductor 1222, lower left contact of cam 1006, conductor 1007, winding of relay 1224, right back contact of relay 1225, resistance 1226, conductor 1227, brush 806 and its first terminal cross connected as shown, resistance 854, conductor 851, upper left contact of cam 1008, conductor 1009, winding of relay 1427, winding of relay 1428, conductor 1429, upper left contact of cam 1010, conductor 1426, back contact of relay 1420, conductor 1223, inner left front contact of relay 1220, conductor 690, lower contact of cam 689, conductor 688,

district selector brush 120, ring conductor 214, upper right and lower left contacts of cam 204 to ground. During the time that the incoming selector is returning to normal after being released by a district selector or by an office selector, ground is connected to the tip conductor 213, over the lower left contact of cam 202 and the upper left contact of cam 201, and to the ring conductor 214, over the lower left and upper right contacts of cam 204 so that during the interval between release and normal it is impossible for relay 1224 to operate. When the incoming selector reaches normal, the above traced circuit is completed and relay 1224 operates. Relay 203 cannot operate in series with relay 1224; relay 1428 is polarized and does not operate; and the operation of relay 1427 is ineffective with sequence switch 1000 in position 1.

The operation of relay 1220 also prepares a circuit from ground at the lower right contact of cam 730, conductor 953, left back contact of relay 955, right back contact of relay 954, outer right front contact of relay 1220, to the armatures of relays 1228 and 1224. The front contacts of these armatures are connected in parallel over conductor 1301 to the winding of relay 1300. The operation of relay 1224 therefore completes the circuit of relay 1300 and that relay operates and locks over its inner front contact, lower contacts of cam 1011, inner right front contact of relay 1220, contact 609 of start key 601 to ground. Relays 1228 and 1224 serve the same purpose but with respect to incoming selectors employing 24 volt and 48 volt transmission respectively. For those incoming selectors employing 24 volt transmission the terminals served by brush 1104 are cross-connected to operate relay 1225, which relay transfers the trunk guard test from relay 1224 to relay 1228. The operation of relay 1300 as above described closes a circuit from battery through the winding of sequence switch magnet 1000, lower left contact of cam 1012, outer front contact of relay 1300, lower left contact of cam 1011, inner right front contact of relay 1220, contact 609 of key 601 to ground, advancing sequence switch 1000 to position 2. The advance of sequence switch 1000 out of position 1 opens the locking circuit of relay 1300 and that relay releases.

With sequence switch 1000 in position 2, the fundamental circuit is established extending from battery through the winding of relay 203 and thence as previously traced to the outer left front contact of relay 1220, conductor 1222, lower left contact of cam 1013, conductor 853, brush 805, cross-connected as shown, resistance 852, conductor 851, upper left contact of cam 1008, conductor 1009, winding of relays 1427 and 120

1428, conductor 1429, upper left contact of cam 1010, conductor 1426, back contact of relay 1420, conductor 1223, inner left front contact of relay 1220 and thence as previously traced to ground at the lower left contact of cam 204. Relay 1427 operates in this circuit but relay 1428 is polarized and does not. The operation of relay 1427 closes a counting relay circuit for controlling the incoming brush selection. This circuit may be traced from battery over the upper left contact of cam 1001, conductor 1014, the No. 2 counting relay 1414, back contact of the No. 2' counting relay 1415, conductor 1430, Figs. 14 and 13, contact 1308 of key 1302, contact 1303 of key 1304, lower left contact of cam 1015, left contact of cam 1016, conductor 1017, front contact of relay 1427, conductor 1431, upper right contact of cam 1018 to ground. Relay 1412 operates in this circuit and closes the usual locking circuit for itself through the winding of relay 1415, over the front contact of relay 1414 to ground. Relay 1415 does not operate, being shunted by the energizing circuit of relay 1414 in the usual manner.

Relay 203 also operates in the fundamental circuit and closes a circuit from battery through the right winding of relay 206, upper left contact of cam 207, lower left contact of cam 208, front contact of relay 203, lower right contact of cam 209 to ground. Relay 206 closes a locking circuit for itself through its right winding, lower contact of cam 215, right front contact of relay 206, upper right contacts of cam 207, lower right contact of cam 208, front contact of relay 203, to ground at the lower right contact of cam 209. The operation of relay 206 closes a circuit from battery through the winding of sequence switch magnet 200, lower left contact of cam 216, left front contact of relay 206, upper left contact of cam 209 to ground, advancing sequence switch 200 to position 2.

With sequence switch 200 in position $1\frac{3}{4}$ to 2 ground is intermittently connected to the tip conductor 213 from the upper right contact of cam 210, over commutator brush 211, commutator strip 212, upper left contact of cam 202, and the upper left contact of cam 201. This circuit holds relay 203 operated and shunts the stepping relay 1427 of the test circuit. The first closure of this circuit permits the operation of relay 1415 in the usual manner. Relay 1415 in operating extends the counting relay circuit over its front contact, back contact of relay 1437 to the back contact of relay 1417 and the winding of relay 1416. Relay 1416 operates on the next operation of relay 1427 and locks in the usual manner. The second closure of the commutator circuit permits the operation of relay 1417 which extends the counting relay circuit over its front contact, conductor 1432, left contact of cam 1019, conductor 1020 to the winding of relay 1418. The third closure of the commutator circuit permits the operation of relays 1419 and 1420 in the locking circuit of relay 1418. The operation of relay 1419 closes a circuit from battery through the winding of sequence switch magnet 1000, lower right contact of cam 1022, left back contact of relay 1305, upper contacts of cam 1023, conductor 1024, front contact of relay 1419 to ground. Sequence switch 1000 advances to position 3 in this circuit.

The operation of relay 1420 opens the circuit of relay 203 and that relay releases in turn releasing relay 206. The release of relay 206 closes the circuit from battery through the winding of sequence switch magnet 200, upper right and lower left contacts of cam 217, left back contact of relay 206, upper left contact of cam 209 to ground, advancing sequence switch 200 to position 3.

The advance of sequence switch 1000 from position 2 opens the battery feed circuit for the counting relays and they release. Relay 1419 closes at its back contact of circuit from battery through the winding of sequence switch magnet 1000, lower right contact of cam 1022, left back contact of relay 1305, right contacts of cam 1023, conductor 1025, back contact of relay 1419 to ground, advancing sequence switch 1000 to position 4.

As soon as sequence switch 200 arrives in position 3 a circuit is closed for trip magnet 218 over the lower right contact of cam 210 to ground, in preparation for tripping the desired set of brushes. With sequence switch 200 in position 3 and switch 1000 in position 4 the previously traced fundamental circuit is reestablished, the operation of relay 203 operating relay 206. The operation of relay 206 advances sequence switch 200 to position 4 in the same circuit as advanced it to position 2.

With sequence switch 200 in position $3\frac{3}{4}+4$ the intermittent commutator circuit extends from the tip conductor 213 over the upper left contact of cam 201, upper right contact of cam 202, commutator strip 220, brush 219 to ground on the upper right contact of cam 210. The up-drive magnet is energized in position 4 over the left front contact of relay 206, advancing the incoming selector in a group selecting operation.

This operation is essentially the same as the brush selecting operation. The operation of stepping relay 1427 in the fundamental circuit completes a counting relay circuit which extends from ground as previously described to cam 1015 and thence over the lower right contact of cam 1015, the inner upper right normal contact of keys 1304 and 1302, the conductor 1435, Figs. 13 and 14, the back contact of relay 1413, through winding of the No. 3 counting relay 1412 to battery.

over conductor 1327 and the right contact of cam 1001. The counting relays operate successively until relays 1419 and 1420 operate. As before the operation of relay 1419 advances sequence switch 1000, this time to position 5, and the advance of the sequence switch opens the counting relay circuit to release relay 1419 and advance the sequence switch to position 6. Relay 1420 opens the fundamental circuit as before and the release of relays 203 and 206 brings the selector to rest on the first trunk of the selected group and advances sequence switch 200 to position 5. An auxiliary circuit is closed for relay 206 during group selection which may be traced through the right winding of relay 206, upper right and lower left contacts of cam 205, lower left and upper right contacts of cam 207, commutator strip 228, brush 229, upper right contact of cam 230, left front contact of relay 206, upper left contact of cam 209 to ground which insures the centering of the brush set on the outgoing trunk before the release of relay 206.

With sequence switch 200 in position 5 a local circuit is closed for relay 206 extending from battery through resistance 225, left winding of relay 206, lower left contact of cam 209 to ground. Relay 206 operates in this circuit and closes a circuit from battery through its right winding, lower left contact of cam 215, right front contact of relay 206, upper right contact of cam 207, upper left contact of cam 208, to sleeve brush 224. If the final selector connected to the first set of terminals of the selected group is busy, relay 206 will be held operated in this circuit. The operation of relay 206 closes the previously traced circuit for sequence switch 200 advancing it to position 6, in which position the holding circuit of relay 206 to the sleeve brush 224 is maintained.

With sequence switch 200 in position 6 the up-drive magnet is again energized and the selector advances in the trunk hunting movement. As soon as the idle trunk is found, the holding circuit of relay 206 is opened and that relay releases, connecting ground over the lower contact of cam 226, right back contact of relay 206, upper right contact of cam 207, upper left contact of cam 208 to sleeve brush 224 to render the final circuit busy to other incoming selectors. With relay 206 released the previously traced circuit is closed over the back contact of relay 206 advancing sequence switch 200 to position 8.

As soon as sequence switch 200 reaches position 6½ direct ground is connected over the upper left contact of cam 210 to brush 224 to hold the final selector busy. The commutator strip 228 functions at this time in the same manner as it did in group selection to center the brush set. During the trunk hunting operation sequence switch 1000 has remained in position 6.

As soon as switch 200 reaches position 8 the fundamental circuit is reestablished extending as before through the winding of relay 203 to battery and over the contacts of cam 204 to ground. With sequence switch 200 in position 8 and with relay 203 operated a circuit is also established from battery through the right winding of relay 206, upper left contact of cam 207, lower left contact of cam 208, front contact of relay 203, lower left contact of cam 231, brush 222 to the tip conductor 301 of the final selector and thence over the lower left and upper right contacts of cam 303, resistance 304, lower right contact of cam 305, right winding of relay 306, right contacts of cam 307 to ground.

A circuit in parallel with the right winding of relay 206 is closed from battery through resistance 225 and the lower left contact of cam 207 to the circuit just traced. The effect of this second circuit is to prevent the operation of relay 206 at this time. However, relay 306 operates and closes a locking circuit for itself extending as previously traced through its right winding, right contacts of cam 308, left front contact of relay 306, lower contacts of cam 209, right contact of cam 310 to ground. It also closes a circuit from battery through the winding of relay 312 lower contacts of cam 313, to ground at the right front contact of relay 306. Relay 312 operates and closes the locking circuit for itself through its winding, the upper contacts of cam 327, left front contact of relay 312, left contacts of cam 331, contact 352 of jack 353, sleeve conductor 354, incoming selector sleeve brush 224, upper left contact of cam 210 to ground, holding relay 312 operated until switch 300 leaves position 6. The operation of relay 312 at this time closes a circuit from battery through the winding of sequence switch 300, lower right and upper left contacts of cam 314, right front contact of relay 312 to ground, advancing sequence switch 300 to position 2.

With sequence switch 300 in position 2, the high speed up-drive magnet 315 is energized in a circuit over the upper right contact of cam 316, lower right contact of cam 313, right front contact of relay 306 to ground. A circuit is also prepared from ground over the upper right contact of cam 317, brush 318, commutator strip 319, right contacts of cam 320, ring conductor 302 of the final selector, brush 223, upper left and lower right contacts of cam 232, to the tip conductor of the incoming selector and over the upper left contact of cam 201, lower right contact of cam 202, winding of relay 203 to battery. This circuit serves to hold relay 203 operated and shunts the stepping relay of the test circuit in the usual manner during the advance of the final selector in

its brush selecting operation. A counting relay circuit is established by the operation of relay 1427, similar to those previously traced. Relays 1419 and 1420 in operating 5 perform their usual functions advancing sequence switch 1000 to position 7 and releasing relay 203. The release of relay 1419 advances sequence switch 1000 to position 8 and the release of relay 203 causes the release 10 of relays 206 and 306 closing a circuit from battery through the winding of sequence switch magnet 300, lower right contact of cam 321, right back contact of relay 306 to ground advancing sequence switch 300 to position 3. The release of relay 306 also 15 opens the circuit of the high speed up-drive magnet and the selector is brought to rest in position to select the desired set of brushes.

With sequence switch 300 in position 3 the tripping magnet 311 is energized over the lower right contact of cam 317. Final tens selection takes place in the manner just described, after which switch 1000 is advanced 20 to position 10 and switch 300 to position 5. The final units selection takes place in position 6 of switch 300 and differs from the tens selection only in the use of low speed up-drive magnet 324 instead of the high speed up-drive magnet and of course in the use of the proper commutator strip. The release of relay 306 following units selection advances sequence switch 300 to position 7 in a circuit through the winding of the sequence 25 switch magnet, lower contacts of cam 314, right back contact of relay 306 to ground.

In position 7 a circuit is closed for advancing sequence switch 300 to position 9, extending over the upper contacts of cam 313, upper right contact of cam 317 to ground. As sequence switch 300 moves through position $6\frac{3}{4} + 8$, a circuit is closed from ground through the winding of relay 322, right contacts of cam 331, sleeve brush 332, sleeve of the test line on which the final selector has been positioned, lower left contact of cam 401, winding of relay 402 to battery.

When sequence switch 300 arrived in position 6 a second locking circuit for relay 312 was closed extending through the winding of relay 312, upper right contact of cam 327, upper left contact of cam 328, back contact of relay 329 to ground at the right front contact of relay 312. The operation of relay 322, therefore, closes the circuit in positions $7\frac{1}{2}$ to 8 from battery through the left winding of relay 306, lower left contact of cam 326, right winding of relay 306, front contact of relay 322, upper contacts of cam 314, right front contact of relay 312 to ground. Relay 306 operates in this circuit and closes a locking circuit for itself through its two windings, right contacts of cam 308, left front contact of relay 306, lower contacts of

cam 309, right contact of cam 310 to ground, which is effective until sequence switch 300 leaves position $9\frac{3}{4}$.

The release of relay 306 following units selection connected ground to ring conductor 302 by way of the lower contacts of cam 320, left back contact of relay 306, lower contacts of cam 309, upper right contact of cam 310 to ground. As soon as sequence switch 300 reached position 7, a substitute ground 75 was connected to conductor 302 from the upper left contact of cam 317.

In positions $8 + 8\frac{1}{4}$ ground is connected to tip conductor 301 over the left contacts of cam 303, right contacts of cam 313, upper 80 right contact of cam 317 to ground. The ground connected to ring conductor 302 completes a circuit over brush 223, upper left and lower right contacts of cam 232, upper left contact of cam 201, lower right contact of cam 202, winding of relay 203 to battery causing the operation of relay 203. With relay 203 operated, the ground connected to tip conductor 301 completes a circuit extending over brush 222, lower left 90 contact of cam 231, front contact of relay 203, lower left contact of cam 208, upper left contact of cam 207, right winding of relay 206 to battery. The current in this circuit is sufficient to operate relay 206 which thereupon closes a circuit over from battery through the winding of sequence switch magnet 200, lower left contact of cam 216, left front contact of relay 206, upper left contact of cam 209 to ground, advancing sequence switch 200 to position 9. Relay 206 releases when sequence switch 200 leaves 95 position 8.

Following final units selection sequence switch 1000 was advanced to position 12. 105 With sequence switch 1000 in position 12, a non-operate test is made of relay 203. For this purpose a circuit is established from battery through the winding of relay 203, upper contacts of cam 204, conductor 214 and thence as previously traced to conductor 1223, back contact of relay 1420, conductor 1426, lower contact of cam 1010, winding of relay 1309, non-operate resistance 1229, right normal contact of relay 1230, lower contact of cam 1008, conductor 851, resistance 854, through the cross-connecting racks to the No. 1 terminal of brush 806, conductors 1227 and 1231, lower right contact of cam 1013, conductor 1222 and thence as previously traced to conductor 213, upper left contact of cam 201, lower left contact of cam 202 to ground. Relay 203 should not operate in this circuit but relay 1309 should. The operation of relay 1309 closes a circuit from battery over the upper left contact of cam 1001, conductor 1014, winding of relay 1418, conductor 1441, Figures 14 and 10, lower contact of cam 1029, upper right contact of cam 1016, conductor 1434, inner right back 110 115 120 125 130

contact of relay 1433, conductor 1431, front contact of relay 1309, conductor 1025 to ground at the back contact of relay 1419. Relay 1418 operates and closes the usual locking circuit for itself through the windings of relays 1419 and 1420 which relays do not operate since they are shunted by the energizing circuit of relay 1418. A circuit is also closed from battery through the winding and normal contact of relay 1305, right contacts of cam 1013, conductor 1434, inner right normal contact of relay 1433, conductor 1431, front contact of relay 1309, conductor 1025 to ground at the back contact of relay 1419. Relay 1305 operates and locks over its right front contact, lower contact of cam 1032 to ground. The operation of relay 1305 closes a circuit from ground at the back contact of relay 1419, right contacts of cam 1023, inner left front contact of cam 1035, contact of interrupter 1310, lower contact of cam 1033, conductor 1442, Figures 10 and 14, back contact of relay 1401, winding of relay 1400, conductor 1027 to battery at the right contact of cam 1001. Relay 1400 operates and closes the usual locking circuit for itself through relay 1401 to ground at the outer back contact of relay 1433. When interrupter 1310 opens its contact relay 1401 is permitted to operate in this locking circuit. On the next closure of the interrupter contact, relay 1402 operates and on the next opening relay 1403 operates. The counting relay circuit is extended from the No. 8 pair to the No. 7 pair by a circuit over the front contact of relay 1403, left back contact of relay 1440, right back contact of relay 1437 to the armature of relay 1405. The third closure and opening of interrupter contact causes the operation of relays 1404 and 1405, the next of relays 1406 and 1407 and the next of relays 1408 and 1409. Following the operation of relay 1409, ground over the front contacts of the prime counting relays 1401, 1403, 1405 and 1407, is extended over the front contact of relay 1409, conductor 1438, back contact of relay 1306, conductor 1307, upper contact of cam 1028, winding of relay 1300 to battery. Relay 1300 operates and locks over its inner front contact to the lower right contact of cam 1026. It also closes a circuit from battery through the winding of sequence switch magnet 1000, lower left contact of cam 1012, outer front contact of relay 1300, upper contact of cam 1011 to ground, advancing sequence 1000 to position 13. The advance of sequence switch 1000 opens the circuit of relays 1309, 1300 and 1305 and the counting relays so that these relays release.

If relay 203 does operate falsely during this interval it will advance the incoming selector sequence switch as will be described later and open the circuit of relay 1309. The release of relay 1309 opens the ener-

gizing circuit of relay 1418 and permits relays 1419 and 1420 to operate. The operation of relay 1419 disconnects ground from interrupter 1310 and halts the operation of the counting relays under the control of interrupter 1310. In consequence no circuit is established for relay 1300 and sequence switch 1000 is not advanced from position 12. After a time interval an alarm will be sounded and the attendant notified. 75

If relay 203 has not operated, the advance of sequence switch 1000 to position 13 changes the fundamental circuit to extend over conductor 1223, back contact of relay 1420, conductor 1426, upper left contact of cam 1010, conductor 1429, windings of relays 1428 and 1427, conductor 1009, upper left contact of cam 1008, conductor 851, resistance 852, cross-connected to the first terminal of brush 805, conductor 853, lower left contact of cam 1013 to conductor 1222. This circuit does not include resistance 1229 and relay 203 should operate in this circuit. Relays 1427 and 1428 also operate. The operation of relay 1428 closes a circuit from ground at its front contact, upper contacts of cam 1044, conductor 1017, front contact of relay 1427, inner back contact of relay 1433, conductor 1434, upper right contact of cam 1016, lower contact of cam 1029, conductor 1441, Figs. 10 and 14, winding of relay 1418, conductor 1014 to battery at the upper left back of cam 1001. 35

The operation of relay 203 closes a circuit from battery through the right winding of relay 206, upper left contact of cam 207, lower left contact of cam 208, front contact of relay 203, lower right contact of cam 209 to ground. Relay 206 operates and closes a circuit from battery through the winding of sequence switch magnet 200, lower left contact of cam 216, right front contact of relay 206, upper left contact of cam 209 to ground, advancing sequence switch 200 from position 9. The above traced circuit of relay 206 is 105 opened when sequence switch 200 leaves position 10 so that the circuit of sequence switch 200 is also opened and the switch comes to rest in position 11. When switch 200 leaves position 10 the circuit of relay 203 is 110 opened at cam 204 so that relay 203 releases as well as relays 1428 and 1427 in the test circuit. When sequence switch 200 comes to rest in position 11, relay 205 is 115 connected to the trunk conductors. The circuit may be traced from battery through the right winding of relay 205, upper winding of coil 233, left contacts of cam 244 upper left winding of repeating coil 241, upper right and lower left contacts of cam 232 to 120 conductor 213. The circuit of the left winding of relay 205 may be traced from ground over the lower right contact of cam 209, back contact of relay 203, lower left and upper right contacts of cam 254, left winding of re- 125 130

lay 205, lower winding of coil 233, lower left and upper right contacts of cam 243, lower left winding of repeating coil 241 to conductor 214.

5 The opening of the fundamental circuit by the advance of sequence switch 200 and the consequent release of relays 1427 and 1428 permits the operation of relays 1419 and 1420. The operation of relay 1419 closes a 10 circuit from battery through the winding of sequence switch magnet 1000, lower right contact of cam 1022, left back contact of relay 1305, upper contacts of cam 1023, conductor 1024, front contact of relay 1419 to 15 ground, advancing sequence switch 1000 to position 14. The advance of the sequence switch releases the counting relays as usual. If relay 203 should fail to operate, relays 1419 and 1420 cannot operate and sequence 20 switch 1000 remains in position 13 until the trouble switch causes an alarm to sound.

When sequence switch 1000 arrives in position 14, a circuit is closed from battery through the winding of relay 1035, lower 25 contacts of cam 1044, conductor 1024, outer left back contact of relay 1313, lower left contact of cam 1018 to ground. Relay 1305 operates and closes a circuit from battery through the winding of relay 1444, back contact 30 of relay 1445, right back contact of relay 1311, upper left contact of cam 1033, contact of interrupter 1310, inner left front contact of relay 1305, upper contacts of cam 1023, conductor 1024, outer left back contact 35 of relay 1313, lower left contact of cam 1018 to ground. Relay 1444 operates when interrupter 1310 closes its contact and closes a locking circuit for itself through the winding of relay 1445, front contact of relay 40 1444, lower contact of cam 1035 to ground. When the interrupter opens its contact, relay 1445 operates in the locking circuit of relay 1444. The operation of relay 1445 closes a circuit from battery through the 45 winding of relay 1446 to ground at the front contact of relay 1445. Relay 1446 in operating completes a circuit from battery through the winding of relay 1437, back contact of relay 1443, inner lower left normal contact of key 1304, inner right front contact 50 of relay 1446 to ground at the front contact of relay 1445. With relay 1437 operated, a circuit is closed from battery through the winding of sequence switch magnet 1000, lower right contact of cam 1022, inner left front contact of relay 1437 to ground at the front contact of relay 1445. Sequence 55 switch 1000 is advanced to position 15 of this circuit. Position 14 is reserved for a test applicable only to three-wire incoming selectors which will not be described. The advance of sequence switch 1000 opens the circuits of relays 1444, 1445, 1446 and 1437 but relay 1305 remains locked over its right

front contact to ground at the lower contact 60 of cam 1032.

It will be remembered that relay 205 was connected to the trunk conductors 213 and 214 with sequence switch 200 in position 11, battery through the right winding being 70 connected to conductor 213 and ground through the left winding being connected to conductor 214. When sequence switch 1000 arrives in position 15, the fundamental circuit through relay 205 will be completed 75 as follows: Conductor 1222, upper left contact of cam 1013, outer upper left normal contact of key 1302, conductors 1231 and 1227, brush 806 and its corresponding terminal, resistance 854, conductor 851, right 80 contact of cam 1008, outer left back contact of relay 1312, winding of relay 1309, resistance 1229, normal contact of relay 1230, inner left back contact of relay 1312, right 85 contact of cam 1010, conductor 1426, back contact of relay 1420 to conductor 1223. The current in this circuit is in the right direction to operate relay 1309 and this relay closes a circuit from battery through the winding of relay 1418, conductor 1441 Figs. 90 14 and 10, lower contact of cam 1014, upper right contact of cam 1016, conductor 1434, inner right back contact of relay 1433, front contact of relay 1309, conductor 1025 to ground at the back contact of relay 1419. 95 At the same time a circuit is closed from ground at the back contact of relay 1419, conductor 1025, right contacts of cam 1023, inner left front contact of relay 1305, interrupter 1310, lower contact of cam 1033, 100 conductor 1442, Figs. 10 and 14, back contact of relay 1401, winding of relay 1400 to battery. Under the control of interrupter 1310, the Nos. 9, 8, 7, 6 and 5 pairs of counting relays will be operated. The operation of 105 relay 1409 (No. 5') extends the ground connected to conductor 1442, over the front contact of relay 1409, conductor 1438, back contact of relay 1306, conductor 1307, over the lower left contact of cam 1028, inner left back 110 contact of relay 1313, winding of relay 1312 to battery, and over the upper left contact of cam 1028 to the winding of relay 1300 and battery. Relays 1300 and 1312 operate, relay 1312 locking over its right contact to ground at the upper left contact of cam 1032. This locking circuit remains closed until sequence switch 1000 leaves position 16. The operation of relay 1300 closes a circuit from battery through the winding of sequence switch magnet 1000, lower left contact of cam 1012, outer front contact of relay 1300, upper left contact of cam 1011 to ground, advancing sequence switch 1000 to position 16. The operation of relay 1312 reverses the current 120 through relay 1309 and that relay releases permitting the operation of relays 1419 and 1420 but the simultaneous advance of se- 125

quence switch 1000 renders the operation of these relays ineffective. If relay 205 has failed to operate in the circuit through relay 1301, sequence switch 1000 will not be advanced from position 16 in the manner to be described. No further operations occur in the test circuit until the incoming selector has been advanced to talking position due to the tests performed by the test line.

10 The use of polarized relay 1309 in the fundamental circuit with sequence switch 1000 in position 15 serves to distinguish the reversed connection of relay 203 due to the correct functioning of the final selector from 15 that due to the advance of that selector to tell-tale following units selection. In the latter case the operation of the counting relays releases relay 203 as usual. When the selector reaches tell-tale position, a circuit 20 is closed from battery through the winding of sequence switch magnet 300, upper left contact of cam 321, tell-tale commutator segment 344, brush 318, upper right contact of cam 317 to ground. Sequence switch 300 is 25 immediately advanced to position 12. The advance of the sequence switch releases relay 306 and causes the operation of relays 203 and 206, the advance of sequence switch 200, and the reversed connection of relay 203, as described. Relay 312 is released in position 11 and reoperated in position 12, since no circuit is provided for relay 306 over the sleeve terminal at tell-tale. Relay 312 locks to sleeve conductor 354 in positions 12+14 and 30 advances sequence switch 300 to position 13. In position 13, relay 312 causes the down drive magnet to restore the final selector to normal, whereupon a circuit is closed for advancing the sequence switch to position 40 14. In position 14 relay 306 is intermittently operated under the control of interrup- 45 ter 338 to connect a tone to conductor 302.

In the meantime, the non-operate and operate tests of relay 203 and the operate test of relay 205 have progressed as described. Relay 1309 operates in the fundamental circuit through relay 205, operating relay 1418 and preparing circuits for relays 1419 and 1420 as usual. Following the operation of 50 relay 205, sequence switch 200 is advanced to position 13 and the supervisory relay connected through to conductor 302. The intermittent operation of relay 306 therefore causes the intermittent operation of relays 55 240 and 206 and the periodic reversal of the connection of relay 205 to the trunk. This reversal will release relay 1309, permitting the operation of relays 1419 and 1420. Relay 1419 will remove ground from 60 conductor 1025, thus stopping the operation of the counting relays and preventing the advance of sequence switch 1000 to position 16.

When sequence switch 300 arrived in position 8½ during the normal operations pre- 65 viously described, a circuit was closed from battery through the winding of relay 402, left contact of cam 401, brush 323, upper right and lower left contacts of cam 331, left front contact of relay 312, left contact of cam 330, winding of relay 329, lower contact of cam 310 to ground, for the purpose of testing whether this is one of a PBX group. A test line would ordinarily not be one of the PBX group and we will assume that full battery potential is present on the sleeve terminal so that relay 329 operates. The operation of relay 329 opens the locking circuit of relay 312 and that relay releases.

The release of relay 312 closes a circuit from battery through the winding of sequence switch magnet 300, lower left contact of cam 321, back contact of relay 312 to ground advancing sequence switch 300 to position 12. As sequence switch 300 passes from position 9¾ to position 10¾ the locking circuit of relay 306 extends from its left front contact over the lower contacts of cam 309, resistance 332, upper left and lower right contacts of cam 333, left back contact of relay 312, lower left and upper right contacts of cam 331 to sleeve brush 323, testing the line for busy condition. Assuming that the test line is idle, relay 306 will immediately be released. The release of relay 306, connects ground over the upper left contact of cam 317, left back contact of relay 306, lower contacts of cam 309, resistance 332, upper left and lower right contacts of cam 333, left back contact of relay 312, lower left and upper right contacts of cam 331 to sleeve brush 323, to hold the test line busy. When sequence switch 300 arrives at position 12, ground is connected over the lower left contact of cam 317, through resistance 334, left contacts of cam 333 to sleeve brush 323, to hold the line busy while in use. With relay 303 released and sequence switch 300 in position 12, relay 312 is operated in a circuit through its winding, upper right contact of cam 327, upper right contact of cam 328, to ground at the right back contact of relay 306. The operation of relay 312 closes a circuit from battery through the winding of sequence switch magnet 300, lower right and upper left contacts of cam 314, right front contact of relay 312 to ground, advancing the sequence switch to position 13 which is talking position.

When ground was connected to sleeve brush 323, as previously described, relay 402 operated and closed an obvious circuit for operating relay 403. The operation of relay 403 closes a circuit from battery over the upper contact of cam 404, right back contact of relay 405, left winding of relay 406, left back contact of relay 405, lower left contact of cam 407, left front contact of relay 403 to ground. Relay 406 operates and closes

100

105

110

115

120

125

130

a locking circuit for itself which may be traced from battery through its right winding and outer left front contact, resistance 408, winding of relay 409, lower left contact of cam 407 to ground at the left front contact of relay 403. Relay 409 operates in this locking circuit and closes a circuit from battery through the winding of relay 410, right contact of relay 409, inner left back contact of relay 411, left back contact of relay 412, upper right contact of cam 413 to ground. Relay 410 in turn closes a circuit from battery through the winding of relay 405, right front contact of relay 410, inner right front contact of relay 403 to ground. Relay 405 locks over its left front contact, lower left contact of cam 407 to ground at the front contact of relay 403. It also closes an obvious circuit for relay 414. Relay 414 connects relay 411 over the lower contacts of cam 415 to tip conductor 416 for the purpose of detecting the presence of generator ground from the incoming selector. It also connects the ring conductor 451 over the upper left contact of cam 452, left front contact of relay 410, outer left front contact of relay 414, upper left contact of cam 417, resistance 418, lower right contact of cam 421 to the inner left armature of relay 406 and thence over the inner left front contact and left winding of relay 406, outer right front contact of relay 405, condenser 454, resistance 455, right contacts of cam 453 to ground for the purpose of detecting the presence of ringing current on the ring conductor from the incoming selector.

Returning to the incoming selector, Fig. 2, it will be remembered that relay 205 was connected to the tip and ring conductors 213 and 214 in position 11 of sequence switch 200. Due to the closure of the fundamental circuit through the test circuit, relay 205 operated closing a circuit from battery through the right winding of relay 206, upper left contact of cam 207, lower right contact of cam 208, front contact of relay 205, lower left contact of cam 201, lower left contact of cam 202 to ground. Relay 206 locks over the lower contact of cam 215, right front contact of relay 206, upper right contact of cam 209 to ground. It also closes a circuit from battery through the winding of sequence switch magnet 200, lower left contact of cam 216, left front contact of relay 203, upper left contact of cam 209 to ground, advancing sequence switch 200 to position 12. The advance of sequence switch 200 opens the locking circuit of relay 206 and that relay releases.

In positions 12 and 13, the ringing source 234 is connected steadily over the left contact of cam 235 through the winding of relay 237, right back contact of relay 206, right contacts of cam 238 to the ring conductor

of the final selector and the test line. An operating circuit is provided for relay 206 in position 12 and positions 13+14½ through its left winding to ground at the lower left contact of cam 209. The operation of this relay is prevented, however, by a shunt over the upper right and lower left contacts of cam 217, back contact of relay 237, left back contact of relay 206, upper left contact of cam 209 to ground.

When sequence switch 200 arrived in position 11½ generator ground was connected over the right contact of cam 231 to the tip conductor of the final selector and the test line.

With sequence switch 200 in position 12, the closure of the upper contact of interrupter 253 completes a circuit from battery through the right winding of relay 206, upper left and lower right contacts of cam 207 to ground through the interrupter contact. The operation of relay 206 advances sequence switch 200 to position 13, relay 206 releasing as the switch advances. With sequence switch 200 in position 13, the closure of the lower contact of interrupter 253 completes a circuit over the upper left and lower right contacts of cam 264, lower left contact of cam 216, winding of sequence switch magnet 200 to battery advancing the sequence switch to position 14. In position 14 ringing current is connected through interrupter 236 over the right contact of cam 235 and through the winding of relay 237 to the ring conductor.

When steady ringing current is connected to the ring conductor in position 12 of sequence switch 200, it is conducted to the left winding of relay 406 in the circuit previously traced. The windings of relay 406 are so arranged that when the ringing current, which is alternating in character, approaches a negative maximum, relay 406 will be released differentially. The release of relay 406 extends the circuit for the ringing current over its left back contact, lower contact of cam 450, condenser 422, winding of relay 423, upper left contact of cam 413 to ground. Relay 423 is an alternating current relay and operates as a further indication of the presence of ringing current. The release of relay 406 also opened the circuit through relay 409 and that relay in turn released. The release of relay 409 opens the circuit of relay 410 but that relay is slow to release. As previously mentioned, relay 411 is connected to tip conductor 416 to which generator ground is connected at the incoming selector. If generator ground is present relay 411 will operate.

With relays 423 and 411 operated, a circuit is closed from battery through the winding of relay 424, outer right front contact of relay 411, left contact of cam 425, front contact of relay 423, lower contact of cam 426 to

ground. Relay 424 locks over its inner right front contact, right contact of cam 407 to ground at the left front contact of relay 403.

With relay 424 operated the complete release of relay 410 closes a circuit from battery through the winding of sequence switch magnet 400, upper right contact of cam 427, outer right front contact of relay 424, left contact of cam 428, right front contact of relay 414, right back contact of relay 410, inner right front contact of relay 403 to ground, advancing sequence switch 400 to position 2. The operation of relay 411 also opens the circuit of relay 410 so that it is necessary that relay 423 operate before relay 410 completely releases in order that relay 424 may operate and advance the sequence switch to position 2. The advance of sequence switch 400 to position 2 therefore indicates the presence of steady ringing current and of generator ground on the tip and ring conductors.

With sequence switch 400 in position 2, a circuit is closed from tip conductor 451 over the upper left contact of cam 452, back contact of relay 410, upper contact of cam 421, condenser 422, winding of relay 423, left contacts of cam 415 to ring conductor 416. This circuit is completed before the end of the immediate ringing period and relay 423 operates. The operation of relay 423 closes a circuit for relay 429 extending from battery through the winding of that relay, upper right contact of cam 425, front contact of relay 423, right back contact of relay 414 to ground. Relay 429 in turn closes a circuit from battery through the winding of relay 411, left front contact of relay 429, upper left contact of cam 430 to ground. Relay 411 in operating closes a circuit from battery through the right winding of relay 406, middle right contact of relay 411, lower right contact of cam 413 to ground. Relay 406 operates in this circuit and prepares a second circuit for itself through its right winding and outer left front contact, through the winding of relay 409, lower left contact of cam 407 to ground at the left front contact of relay 402. Relay 409 does not operate, being shunted by the circuit closed by relay 411. At the end of the immediate ringing period, ringing current is disconnected from the ring conductor for a period and relay 423 releases. The release of relay 423 opens the circuit of relay 429 but this relay is also slow to release and does not, if this open period following immediate ringing is not of sufficient duration. When relay 429 opens its contacts, relay 411 also releases, removing the shunt from the winding of relay 409 and permitting that relay to operate in series with the right winding of relay 406. The operation of relay 409 causes the operation of relays 410, 405 and 414 in the manner previously described.

The operation of relay 410 opens the operating circuit of relay 423 and extends the ring conductor 451 over the left front contact of relay 410 to the outer left armature of relay 414. The operation of relay 414 extends this circuit over the upper right contact of cam 417 through resistances 431 and 418, right contact of cam 421, inner left front contact and left winding of relay 406, outer right front contact of relay 405, condenser 418, left contacts of cam 453, upper right and lower left contacts of cam 415 to tip conductor 416. When the next ringing period starts, ringing current is conducted through the left winding of relay 406 in the circuit just described. When the current approaches the maximum point of the negative half cycle, relay 406 is released differentially as previously described and extends the circuit over its left back contact to the upper right contact of cam 415 thus removing the resistance of the winding of relay 406 and condenser 454 from the circuit. Resistances 431 and 418 are just great enough to prevent the operation of the tripping relay 237 of the incoming selector circuit. The release of relay 406 opens the circuit of relay 409 which in turn opens the circuit of relay 410. The non-trip test of relay 237 is applied during the releasing time of relay 410. When that relay opens its contacts the circuit joining the tip and ring conductors is opened and the pretrip test is ended.

The release of relay 410 also closes a circuit from battery through the winding of sequence switch magnet 400, upper right contact of cam 432, right back contact of relay 424, left contact of cam 428, right front contact of relay 414, left back contact of relay 410, inner right front contact of relay 403 to ground, advancing sequence switch 400 to position 3. The release of relay 410 connects relay 423 across the tip and ring conductors in the same manner as it did when switch 400 advanced to position 2. This occurs before the end of the machine ringing period on which the pretrip test was made. The operation of relay 423 operates relays 429 and 411 as before. Relay 411 closes the previously traced circuit for relay 406, shunting the winding of relay 409. At the end of the machine ringing period relay 423 releases, opening the circuit of relay 429 and in turn the circuit of relay 411. As before, the release of relay 411 permits relay 409 to operate in series with the right winding of relay 406 and the operation of relay 409 causes the operation of relays 410, 405 and 414. Relay 414 at this time connects the left winding of relay 406 across the tip and ring conductors in a circuit which may be traced from ring conductor 451, upper left contact of cam 452, left front contact of relay 410, outer left front contact of relay 414, left contact of cam 417, resistance 418, right 130

contact of cam 421, left front contact and winding of relay 406, outer right front contact of relay 405, condenser 454, resistance 455, lower right and upper left contacts of cam 453, upper right and lower left contacts of cam 415 to tip conductor 416. When the next machine ringing period starts the ringing current releases relay 406 differentially in the manner previously described. At this time the release of relay 406 connects the tip conductor to the ring conductor through resistance 418, shunting out condenser 454, and resistance 455. The release of relay 406 causes the release of relay 409 which in turn 15 starts the release of relay 410. With relay 410 released, relay 423 is connected between the tip and ring conductors in a circuit extending from the ring conductor over the upper left contact of cam 452, left back contact of relay 410, upper contact of cam 450, condenser 422, winding of relay 423, left contacts of cam 415 to the tip conductor. The purpose of this circuit is to charge 20 the condenser 422 to prevent the false operation of relay 423 in position 4 when a test is made to see whether ringing current has been removed from the line.

The value of resistance 418 is such that trip relay 237 of the incoming selector 30 should operate when it is bridged across tip and ring conductors. The operation of relay 237 removes the shunt from the left winding of relay 206 and permits that relay to operate. The operation of relay 206, connects the supervisory relay 240 over the right contact of cam 215, right front contact of relay 206, right contacts of cam 238 to the ring conductor. It also opens the ringing 35 circuit, disconnecting ringing current from the ring conductor, and closes a circuit from battery through the winding of sequence switch magnet 200, lower left contact of cam 216, left front contact of relay 206 to ground at the upper left contact of cam 209 advancing sequence switch 200 to position 15.

As soon as sequence switch 200 reaches position 14 1/4 the circuit of relay 240 is extended directly over the upper contacts of cam 238 to brush 223. The circuit of relay 50 240 over the front contact of relay 206 is opened by the release of relay 206 when sequence switch 200 leaves position 14 1/2, but the cuttings overlap sufficiently to maintain an energizing circuit for relay 240. Sequence switch 200 is immediately advanced to position 16 in a circuit over the upper contacts of cam 208, upper left contact of cam 210 to ground. With sequence switch 55 200 in position 16 the circuits of relay 205 may be traced as follows: battery, through the right winding of relay 205, upper winding of coil 233, upper left contact of cam 215, upper right and lower left contacts of cam 245, left back contact of relay 206, lower right and upper left contacts of cam 244,

upper left winding of repeating coil 241, upper right and lower left contacts of cam 232 to conductor 213; from ground, lower right contact of cam 209, back contact of relay 203, lower left and upper right contacts of cam 254, left winding of relay 205, lower winding of coil 233, upper right and lower left contacts of cam 264, right back contact of relay 206, right contacts of cam 243, lower left winding of repeating coil 241 to conductor 214.

When sequence switch 400 arrives in position 4, a circuit is closed from battery over the left front contact of relay 402, upper contact of cam 404, right back contact of relay 405, left winding of relay 406, left back contact of relay 405, lower left contact of cam 407 to ground at the left front contact of relay 403. Relay 406 operates and closes the locking circuit for itself through the winding of relay 409 as previously described. As before, relay 409 operates relays 410, 405 and 414. The operation of relay 405 opens the operating circuit of relay 406 and leaves relay 406 locked in series with relay 409. As before, the operation of relay 414 extends the tip conductor over the upper left contact of cam 452, left front contact of relay 410, outer left front contact of relay 414, upper left contact of cam 417, resistance 418, right contact of cam 421 to the left front contact of relay 406 whence it is extended through the left winding of relay 406, outer right front contact of relay 405, condenser 454, resistance 455, left contacts of cam 453 to ground. If relay 237 has operated and the talking battery has been connected through supervisory relay 240 to the ring conductor, relay 406 will not be released differentially as it was in the case of ringing current.

With sequence switch 400 in position 4, the operation of relay 414 also closes a circuit from battery through the winding of relay 429, middle front contact of relay 414, inner left back contact of relay 433, upper right contact of cam 430 to ground. With relays 409 and 429 operated a circuit is closed from battery over the left front contact of relay 402, upper contact of cam 404, winding of relay 412, outer left back contact of relay 433, left back contact of relay 434, right contacts of cam 435, right front contact of relay 429, outer left back contact of relay 411, left front contact of relay 409 to ground at the lower left contact of cam 413. The operation of relay 412 opens the operating circuit of relay 410 starting it to release.

On the release of relay 410 a second test is made to determine whether ringing current has been disconnected from the line. The same circuit which was previously traced over the back contact of relay 410 is effective at this time to connect relay 423 across the tip and ring conductors. The release of relay 410 also closes a circuit from

battery over the lower right contact of cam 404, winding of relay 433, upper contacts of cam 428, right front contact of relay 414, right back contact of relay 410 to ground at 5 the inner right front contact of relay 403. The operation of relay 433 opens the circuit of relay 429 and that relay starts to release. If relay 423 is not operated by the time relay 429 is released a circuit is closed from 10 battery through the winding of sequence switch magnet 400, lower right contact of cam 432, outer right front contact of relay 433, right back contact of relay 429, outer left back contact of relay 411, front contact 15 of relay 409, lower left contact of cam 413 to ground, advancing sequence switch 400 to position 5. The advance of sequence switch 400 opens the circuits of relays 412 and 433 and these relays release. If the ringing current 20 was still present so that relay 406 had been released in turn releasing relay 409, the above traced circuit for advancing sequence switch 400 would be open at the contact of relay 409 and the test blocked at this point. 25 Likewise, if relay 423 had operated, a circuit would have been closed from battery through the winding of relay 411, lower contact of cam 425, front contact of relay 423, lower contact of cam 426 to ground. The 30 operation of relay 411 would have opened the above traced circuit for advancing sequence switch 400.

With sequence switch in position 5, the polarity of the talking current is tested and 35 a test made of the slow releasing character of relays 410 and 429. The previously traced circuit through the left winding of relay of 406 is again completed and that relay operates and closes the usual circuit through 40 its right winding and the winding of relay 409. Relay 409 in turn operates relays 410, 405 and 414. Relay 414 closes a circuit from battery through the winding of relay 429, middle left contact of relay 414, inner 45 left back contact of relay 433, upper right contact of cam 430 to ground.

Relay 436 is now connected over the left contacts of cam 437, through resistances 420 and 419, lower left contact of cam 421 to 50 the ring conductor 451. This circuit serves to test the polarity of the talking battery at the incoming selector and also to test the continuity of the circuit through resistances 420 and 419 in the test line. The operation 55 of relay 436 in this circuit closes a circuit from battery through the winding of relay 423, upper left contact of cam 413 to ground. Relay 423 in turn closes a circuit from battery through the winding of relay 411, lower 60 contact of cam 425, front contact of relay 423, lower contact of cam 426 to ground. The operation of relay 411 closes a circuit from battery through the winding of sequence switch magnet 400, upper left contact 65 of cam 427, left front contact of relay

411, right front contact of relay 429, lower contact of cam 417, outer left contact of relay 414, left front contact of relay 410, lower contact of cam 452, to ground advancing sequence switch 400 from position 5. 70

It is obvious that if the polarity of the incoming selector is wrong, relay 436 will not be operated and sequence switch 400 will remain in position 5. As switch 400 leaves position 5, the operating circuits of relays 75 436 and 411 are opened but relay 411 is held locked over its inner right contact, upper left contact of cam 426 to ground, testing the locking circuit of relay 411. As the switch leaves position 6 the operating circuits of relays 410 and 429 are opened starting their release. The circuit for advancing switch 400 to position 10 is completed over the front contacts of relays 429 and 410 in series. Hence, if these relays release too 80 rapidly they will open the circuit of magnet 400 before that switch reaches position 8 and switch 400 will come to rest in position 8. If these relays remain operated until the switch starts out of position 8, a circuit 85 is closed in position 9 over the upper contact of cam 407 to the left front contact of relay 403 insuring the advance of the sequence switch to position 10. Sequence switch 400 is then advanced from position 90 10 to position 12 in a circuit over the lower left contact of cam 432.

In order to get the incoming selector test circuit in synchronism with the final multiple test line, the test line circuit now sends 100 out a synchronizing pulse of measured duration prior to starting the supervisory relay test. In positions 8 to 14 of sequence switch 400, ground is connected over the right contact of cam 426 to interrupter 438. 105 On the closure of interrupter 428 this ground is connected to the winding of relay 424 operating that relay intermittently. With sequence switch 400 in position 12 the tip and ring conductors are connected together 110 over the lower left contact of cam 415, upper right contact of cam 437, right back contact of relay 439, resistance 419, left contact of cam 421. This resistance is of such value as to operate and thoroughly "soak" 115 the winding of the supervisory relay 240.

With sequence switch 400 in position 12 the intermittent operation of relay 424 under the control of interrupter 438, causes the operation of relays 412, 433, 440 and 120 441 as follows: The first release of relay 424 closes a circuit from battery over the upper contact of cam 404, through the winding of relay 412, back contact of relay 433, left back contact of relay 434, lower contacts 125 of cam 435, right back contact of relay 424, lower contact of cam 428 to ground. Relay 412 operates and locks over its inner right front contact to ground at the right back contact of relay 440. The next operation of 130

relay 424 closes circuit from battery over the lower right contact of cam 404, winding of relay 433, outer right front contact of relay 412, right back contact of relay 434, 5 lower contacts of cam 442, outer right front contact of relay 424 to ground at the lower contact of cam 428. Relay 433 locks over its inner right front contact to ground. The next release of relay 424 closes a circuit 10 from battery over the left contact of relay 404, winding of relay 440, right back contact of relay 441, left front contact of relay 433 and thence as previously traced to ground through the back contact of relay 424. 15 Relay 440 in operating opens the circuit of relay 412 and that relay releases. The next operation of relay 434 closes a circuit from battery through the winding of relay 441, front contact of relay 440, back contact of 20 relay 412, right back contact of relay 412 and 434 to ground over the front contact of relay 424 as previously traced. On the next release of relay 424 a circuit is closed from battery through the winding of relay 439, 25 outer right front contact of relay 441, left front contact of relay 433, left back contact of relay 434, lower contacts of cam 435, back contact of relay 424 to ground at the lower contact of cam 428. The operation 30 of relay 439 opens the shunt which was closed at its right back contact around resistance 420 and the upper left contact of cam 447, introducing resistance 420 into the circuit of the supervisory relay 240. The 35 value of the combined resistances is such as to cause relay 240 to release. Relay 439 also closes a circuit from battery over the left contact of cam 404, through the winding of relay 434, left back contact of relay 443 over the inner right front contacts of relay 439, over the locking circuit of that relay 40 which extends over the right back contact of relay 444, upper right and lower left contacts of cam 452 to ground. 45 The operation of relay 240 in response to the beginning of the synchronizing impulse closes a circuit from battery through resistance 225, left winding of relay 206, front contact of relay 240, upper right contact of cam 201, lower left contact of cam 202 to ground, operating relay 206. The operation 50 of relay 206 reverses the connection of relay 205 to conductors 213 and 214. With relay 206 operated conductor 214 is extended through the lower left winding of repeating coil 241, right contacts of cam 243, right 55 front contact of relay 206, upper left contact of cam 215, upper winding of coil 233, right winding of relay 205 to battery, and conductor 213 is extended over the lower 60 left and upper right contacts of cam 232, upper left winding of repeating coil 241, upper left and lower right contacts of cam 244, left front contact of relay 206, left contact of cam 230, lower winding of coil 233, left winding of relay 205, upper left and lower right contacts of cam 254, back contact of relay 203, lower right contact of cam 209 to ground. At the completion of the synchronizing impulse the release of relay 70 240 permits the release of relay 206 and the restoration of the original connection of relay 205 to the trunk. 75 With sequence switch 1000 in position 16, the fundamental circuit is established from conductor 1223 over the back contact of relay 1420, conductor 1426, right contact of cam 1010, inner right front contact of relay 1312, winding of relay 1309, resistance 1229, right normal contact of relay 1230, outer 80 left front contact of relay 1312, right contact of cam 1008, conductor 851, resistances 852 and 856, brush 803, conductor 855, right contact of cam 1006 to conductor 1222. Until the supervisory relay 240 is operated 85 causing the reversed connection of relay 205 to the fundamental circuits, relay 1309 remains unoperated but when the reversal takes place relay 1309 is operated since due to the operation of relay 1312 the fundamental circuit extending through relay 1309 is 90 also reversed at this time. 95 With sequence switch 1000 in position 16, a circuit is closed from battery through the winding of relay 1433, conductor 1448, upper left contact of cam 1035 to ground. Relay 1433 in operating closes a circuit from battery through the winding of relay 1437, back contact of relay 1443, inner lower left contact of key 1304, next to the outer front 100 contact of relay 1433 to ground. The operation of relay 1309 with relay 1433 operated closes a circuit from battery through the winding of relay 1447 and over its left normal contact, right normal contact of relay 1446 next to the inner front contact of relay 1423, conductor 1431, front contact of relay 1309, conductor 1025 to ground at the back contact of relay 1419. 105 Relay 1447 locks over its outer alternate contact, back contact of relay 1449 to ground over conductor 1025. With relays 1433 and 1447 operated a circuit is closed from battery over the upper left contacts of cam 1001, conductor 1014, winding of relay 1400, 115 back contact of relay 1401, conductor 1442, Figs. 14 and 12, left back contact of relay 1230, right back contact of relay 1440, upper right contact of cam 1049, upper right contact of cam 1016, conductor 1434, innermost 120 right front contact of relay 1433, interrupter 1450, inner right front contact of relay 1447, back contact of relay 1300, lower right contact of cam 1026 to ground. The closure of the contact of interrupter 1450 operates 125 relay 1400 and the opening permits the operation of relay 1401 in the locking circuit of relay 1400 which extends in the present case over the outermost front contact of relay 1433, back contact of relay 1314, left 130

back contact of relay 1315, over the inner right front contact of relay 1447 to ground as traced for the interrupter circuit. The second closure and opening of interrupter 1450 causes the operation of relays 1402 and 1403 respectively.

With relay 1437 operated as previously described, a circuit is closed in parallel with relay 1403 through the winding of relay 1316 and the inner right front contact of relay 1437. Relay 1316 operates in parallel with relay 1403. Therefore when interrupter 1450 makes its third closure a circuit is closed from battery through the winding of relay 1317, inner left back contact of relay 1318, left back contact of relay 1306, right back contact of relay 1232, outer lower left normal contact of key 1302, outer right front contact of relay 1437, left back contact of relay 1440, front contact of relay 1403, front contact of relay 1401 to ground as previously traced over interrupter 1450. Relay 1317 closes a locking circuit for itself over its left front contact, left back contact of relay 1318, outer right front contact of relay 1447, back contact of relay 1300 to ground at the lower right contact of cam 1026. This circuit is also in shunt of the winding of relay 1318 although a second locking circuit is also closed for relay 1317 extending through the winding of relay 1318, outer right front contact of relay 1317 to ground on conductor 1348. Relay 1317 also closes a circuit from battery through the winding of relay 1404, back contact of relay 1405, inner right front contact of relay 1317, inner left front contact of relay 1447, right normal contact of relay 1446, next to the inner front contact of relay 1433, conductor 1431 and thence to ground over the front contact of relay 1309. If the synchronizing pulse from the test line is of the correct duration it will not cease until the series of operations just described terminating in the operation of relay 1404 is completed.

Provided the synchronizing pulse is now completed relay 1309 will be released by the reversed connection of relay 205 at the incoming circuit in turn releasing relay 1447. The release of relay 1447 will open the shunt around relay 1318 and that relay will operate in the locking circuit of relay 1317. The release of relay 1447 also opens the energizing circuit of relay 1404 and permits relay 1405 to operate in the locking circuit of relay 1404. Likewise the release of relay 1447 opens the locking circuit of the No. 9 and No. 8 pairs of counting relays and these relays release.

It will be remembered that at the termination of the synchronizing pulse relay 434 was operated. This relay closes an obvious locking circuit for itself. The operation of relay 434 transfers the control of relay 424 from the upper set of relays 412, 433, 440

and 441 to the lower set of relays 443, 444, 445 and 446. With relay 439 operated as previously described, the circuit is arranged to give a release and two "soak" and release tests to supervisory relay 240. These are carried out in the following manner:

The circuit of the release resistance has already been described. The first operation of relay 424 under the control of interrupter 438, closes a shunt around resistance 420 at its left front contact over the left contact of cam 420, producing the first "soak" test. The release of relay 424 opens the shunt and makes the second release test and the second operation of relay 424 recloses the shunt and makes the second "soak" test. The first operation of relay 424 also closes a circuit from battery over the upper contact of cam 404 through the winding of relay 443, back contact of relay 445, outer right front contact of relay 434, lower contacts of cam 442, front contact of relay 424 to ground at the lower contact of cam 428. Relay 443 locks over its inner right front contact to ground at the back contact of relay 446. The release of relay 424 closes a circuit from battery over the upper contact of cam 404, winding of relay 445, right front contact of relay 443, inner left front contact of relay 434, lower contacts of cam 435, back contact of relay 424, lower contacts of cam 435, back contact of relay 424, lower contact of cam 428 to ground. Relay 445 locks over its left front contact to ground at the outer right front contact of relay 443. The next operation of relay 424 closes a circuit through the winding of relay 446, right front contact of relay 445 and over the right front contact of relay 434 to ground as previously described.

Relay 446 locks to ground at its left front contact and opens the locking circuit of relay 443. The next release of relay 424 closes a circuit through the winding of relay 444, right front contact of relay 446, left back contact of relay 443, inner left front contact of relay 434 to ground as previously described. Relay 444 locks to ground at its inner right front contact and opens the locking circuit of relay 445. The next operation of relay 424 closes a circuit from battery through the winding of relay 443, back contact of relay 445 to ground as previously described. With relays 443 and 444 both operated, the locking circuit of relay 439 is opened as well as its energizing circuit and relay 439 releases, closing the shunt over its right back contact and the upper right contact of cam 437 around resistance 420 starting the second synchronizing impulse. The release of relay 439 also closes a circuit from battery through the winding of sequence switch magnet 400, lower right contact of cam 427, left back contact of relay 439, outer left front contact of relay 434, inner left

front contact of relay 444 to ground, advancing sequence switch 400 to position 14. The advance of the sequence switch releases relays 444 and 434.

5 With sequence switch 400 in position 14, relay 433 remains locked and the release of relay 424 causes the operation of relay 440 and the operation of relay 424 causes the operation of relay 441 as before. The next 10 release of relay 424 operates relay 439 as previously described and, as before, the operation of relay 439 causes the operation of relay 434. The operation of relay 439 also opens the circuit of the supervisory relay 15 240.

Relay 424 now applies two operate and release tests to supervisory relay 240 by means of a circuit across the tip and ring conductors extending from ring conductor 20 457 over the lower left contact of cam 421, resistance 419, left front contact of relay 424, right contact of cam 447, outer right back contact of relay 444, resistance 448 to the tip conductor 416. The current in this 25 circuit is of that strength which should operate relay 240. During the released period of relay 424, the circuit of relay 240 is open. In response to these two operations of relay 424, relays 443, 445, 446, and 444 are operated 30 successively as previously described.

The operation of relay 444 closes a circuit from battery through the winding of sequence switch magnet 400, lower right contact of cam 432, left front contact of relay 35 439, outer right front contact of relay 434, inner left front contact of relay 444 to ground, advancing sequence switch 400 to position 17. A circuit is then immediately closed over the upper left contact of cam 40 432 and contact 449 of jack 450 to ground, advancing sequence switch 400 to position 18.

The operation of relay 444 also opens the circuit through resistances 448 and 419, releasing supervisory relay 240. Relay 240 45 now remains deenergized, releasing relay 206 and permitting the connection of relay 205 to the tip and ring conductors in the original direction.

The first of the two short "soak" pulses 50 caused by the operation of relay 424 reoperates relay 240 and relay 206, connecting battery through relay 205 to the ring conductor which is the direction necessary to operate relay 1309. Relay 1309 operated 55 causes the operation of relay 1447 as before. The operation of relay 1447 closes a circuit from battery through the winding of the No. 6 counting relay 1406, back contact of relay 1407, front contact of relay 1405, inner 60 right front contact of relay 1317, inner left front contact of relay 1447, right normal contact of relay 1446, next to the inner front contact of relay 1423, conductor 1431, front contact of relay 1309 to ground on conductor 65 1025. The completion of the first "soak"

pulse permits relays 240 and 206 to release connecting battery to the tip conductor, under which condition, relay 1309 releases. The release of relay 1309 permits the operation of relay 1407 in the locking circuit of relay 1406. Similarly, the second short "soak" 70 pulse causes the operation and locking of relays 1408 and 1409. A circuit is closed in parallel with relay 1409 extending through the winding of relay 1306 and the outer left 75 front contact of relay 1437, in which circuit relay 1306 operates. Following the two short "soak" pulses the second synchronizing pulse causes the operation of relay 1309 and in turn of relay 1447. Relay 1447 now remains 80 operated long enough to render the circuit controlled by interrupter 1450 effective as in the case of the first synchronizing pulse. Relays 1400, 1401, 1402 and 1403 are operated under the control of the interrupter, relay 85 1316 being operated in parallel with relay 1403 as before. The next closure of the contact of interrupter 1450 extends a circuit from ground over the front contact of relay 1403, left back contact of relay 1440, outer 90 right front contact of relay 1437, outer lower left normal contact of key 1302, right back contact of relay 1232, left front contact of relay 1306, left back contact and winding of relay 1311 to battery. Relay 1311 operates and locks over its outer left front contact to grounded conductor 1448. The operation of relay 1311 closes a circuit from battery through the winding of relay 1410, 95 back contact of relay 1411, conductor 1029, right front contact of relay 1311, right front contact of relay 1306 conductor 1438, to the front contact of relay 1409, front contacts of relays 1407 and 1405 to ground as previously traced over the contact of relay 1447. The second synchronizing impulse should 100 be completed at this time and relay 1309 released, permitting the operation of relay 1411 in the locking circuit of relay 1410. 105

The first of the two "operate" tests again 110 causes the operation of relay 1309 and relay 1447. The operation of relay 1447 closes a circuit from battery through the winding of relay 1412, back contact of relay 1413, front contact of relay 1411, conductor 1029 115 and thence as previously traced to ground through the contact of relay 1447. The open period following the first operate test permits the release of relay 1447 and the operation of relay 1413 in the locking circuit of relay 1412. Similarly the second operate test and open period causes the operation of relays 1414 and 1415. 120

A circuit is also closed in parallel with relay 1415 extending through the winding of relay 1230 and the right front contact of relay 1318. The operation of relay 1230 transfers the fundamental circuit from resistance 1229 to the winding of relay 1319 125 at the inner right front contact of relay 1319. 130

1230. With relay 240 released, battery is connected through relay 205 to the tip conductor again, and the fundamental circuit is completed to operate relay 1319, but relay 1309 does not operate. With relay 1433 operated and relay 1309 released a circuit is closed from battery through the winding of relay 1449, left front contact of relay 1433, back contact of relay 1309 to ground conductor 1025.

The operation of relay 1319 closes a circuit from battery over the lower left contact of cam 1001, winding of relay 1314, back contact of relay 1315, front contact of relay 1319, upper right contact of cam 1035 to ground. Relay 1230 also closed a circuit from battery through the winding of relay 1416, back contact of relay 1417, conductor 1451, Figures 14 and 12, outer left front contact of relay 1230, right back contact of relay 1440, upper right contact of cam 1016, conductor 1434, inner front contact of relay 1433, contact of interrupter 1450, left back contact of relay 1315, outer right front contact of relay 1230, left back contact of relay 1446, front contact of relay 1449 to grounded conductor 1025.

When the interrupter 1450 opens its contact relay 1417 operates in the locking circuit of relay 1416. The operation of relay 1417 extends the energizing circuit from ground over its front contact, conductor 1432, left contact of cam 1019, conductor 1020 to the winding of relay 1418 and battery. The second closure and opening of interrupter 1450 permits the operation of relays 1419 and 1420 in the locking circuit of relay 1418. The operation of relay 1419 removes ground from conductor 1025. Relay 1419 also closes a circuit from ground over its front contact to conductor 1024, left contacts of cam 1023, right back contact of relay 1313, interrupter 1310, lower right contact of cam 1033, conductor 1442, Figures 10 and 14, back contact of relay 1401, winding of relay 1400 to battery. The No. 9 and No. 8 pairs of counting relays are operated under the control of interrupter 1310. With relay 1403 operated ground is extended as previously traced to the armature of relay 1403 and over the front contact of that relay, left back contact of relay 1440, outer right front contact of relay 1437, outer lower left normal contact of key 1302, right back contact of relay 1232, right front contact of relay 1306, inner right front contact of relay 1311, inner left front contact of relay 1230, winding of relay 1300 to battery. The operation of relay 1300 closes a circuit from battery through the winding of sequence switch magnet 1000, lower left contact of cam 1012, outer left front contact of relay 1300, upper left contact of cam 1011 to ground advancing sequence switch 1000 to

position 17. The advance of the sequence switch releases the counting relays as well as relays 1317, 1318, 1311, 1312, 1300, 1314.

The above traced operations have been based on the assumption that the incoming selector supervisory relay operates correctly. The supervisory relay 240 may fail in any one of the following ways: It may fail to release during the "soak and release" tests which normally cause the operation of the

No. 6 and No. 5 pairs of counting relays. If the supervisory relay does not release when the increased resistance is connected across the trunk conductors only the No. 6 pair of counting relays will operate. During the second synchronizing pulse the No. 9 and No. 8 pairs of counting relays will operate. Since the No. 5 pair of counting relays has not been operated and, in consequence, relay 1306 is still deenergized, the operation of relay 1403 will extend the circuit over its front contact, left back contact of relay 1440, outer right front contact of relay 1437, outer lower left normal contact of key 1302, right back contact of relay 1232, right back contact of relay 1306, left front contact of relay 1318 to the winding of relay 1320. Relay 1320 locks over its left front contact to grounded conductor 1448. It also closes an obvious circuit for lamp 1321 to indicate that the supervisory relay failed on the "soak" test.

The supervisory relay may chatter on the "soak and release" tests. Therefore, in addition to operating the No. 6 and No. 5 pairs of counting relays together with relay 1306, a circuit would be extended over the front contact of relay 1409, conductor 1438, right front contact of relay 1306, right back contact of relay 1311, back contact of relay 1445, winding of relay 1444 to battery, the next release permitting the operation of relay 1445 in the locking circuit of relay 1444 which extends over the front contact of relay 1444, back contact of relay 1316, upper right contact of cam 1035 to ground. The operation of relay 1445 closes a circuit from battery through the winding of relay 1446, front contact of relay 1445 to ground. Relay 1446 operates and locks to the next to the outermost front contact of relay 1433. The operation of relay 1446 opens the circuit controlled by relay 1309 and prevents further counting of test pulses. It also closes a circuit from battery over its right front contact through lamp 1322, back contact of relay 1320 to grounded conductor 1448, indicating that the supervisory relay contacts chatter.

If the supervisory relay fails to operate on the operate test the corresponding counting relays, namely, the No. 3 and No. 2 pairs will not be operated and the cycle of tests will not be completed. If the supervisory relay chatters on the operate tests not only will No. 3 and No. 2 pairs of relays be oper-

ated but relay 1446 will be operated and locked to light lamp 1322 and block the test.

If, following the last operate test, relay 205 of the incoming selector should release for any reason, it would cause the restoration of the incoming selector to normal and would permit the operation of relay 1315 in the locking circuit of relay 1314. The operation of relay 1315 would open the circuit of the No. 1 counting relay and block the test.

If for any reason the connection of relay 205 should be reversed during the period of operation of relays 1416, 1417, 1418, 1419 and 1420, relays 1309 and 1447 would be operated, in turn operating relay 1446. The operation of relay 1446, as before, opens the energizing circuit of relay 1416 and therefore the operating circuit of relay 1418.

In all of the above failures the blocking of the test will permit the trouble timing switch 1200 to bring in an alarm.

With sequence switch 1000 in position 17 the fundamental circuit is closed from conductor 1223 over the back contact of relay 1420, conductor 1426, upper left contact of cam 1010, conductor 1429, winding of relays 1428 and 1427, conductor 1009, upper right contact of cam 1008, conductor 851, resistance 854, brush 806, conductor 1227, resistance 1226, right back contact of relay 1225, winding of relay 1224, conductor 1007, lower right contact of cam 1006 to conductor 1222.

The operation of relay 1420 as previously described opened the fundamental circuit and permitted the release of relay 205. Relay 205 in releasing completes a circuit from battery through the winding of relay 203, upper left and lower right contacts of cam 204 to ground at the back contact of relay 205. Relay 203 operates and closes a circuit from battery through the winding of sequence switch magnet 200, upper right and lower left contacts of cam 208, front contact of relay 203, lower right contact of cam 209 to ground advancing sequence switch 200 to position 18.

When sequence switch 200 leaves position 17, relay 205 is disconnected from the tip and ring conductors and ground is connected to each conductor as previously described. With sequence switch 200 in position 18, a circuit is completed from battery through the winding of down-drive magnet 246, lower right contact of cam 201, lower left contact of cam 202 to ground. The incoming selector is moved downward under the control of the down-drive magnet. When the selector reaches normal, brush 229 makes contact with the normal segment 247 and a circuit is completed from battery through the winding of sequence switch magnet 200, lower right contact of cam 216, commutator segment 247, brush 229, upper right contact of cam 210 to ground, advancing sequence switch 200 to normal.

When sequence switch 200 reaches normal relay 203 is connected to the tip conductor 213 and ground is connected to the ring conductor 214 as previously described. This completes the fundamental circuit which was traced with sequence switch 1000 in position 17 and causes the operation of relay 1224.

Relay 1224 in operating closes a circuit from battery through the winding of relay 1300, conductor 1301, front contact of relay 1224, outer right front contact of relay 1220, right back contact of relay 954, left back contact of relay 955, conductor 953, lower right contact of cam 730 to ground. Relay 1300 locks over its inner left contact to the lower right contact of cam 1026 and closes a circuit from battery through the winding of register 1036, upper left and lower right contacts of cam 1005, outer left front contact of relay 1300, upper left contact of cam 1011 to ground.

Register 1036 in operating closes a circuit from ground at its front contact, left back contact of relay 1004, contact 1233 of key 1234, winding of register 1235 to battery. Register 1235 in turn closes a circuit from ground over its front contact, upper left contact of cam 1012, winding of sequence switch magnet 1000 to battery advancing sequence switch 1000 to position 18.

The advance of the incoming selector from position 17 $\frac{1}{4}$ opened the locking circuit of relay 312 and that relay released, closing a circuit from battery through the winding of sequence switch magnet 300, lower left contact of cam 321, right back contact of relay 312 to ground advancing sequence switch 300 to position 16. Since the test line is already opened relay 306 is deenergized and a circuit is immediately closed from battery through the winding of sequence switch magnet 300, lower right contact of cam 321, right back contact of relay 306 to ground, advancing sequence switch 300 to position 18. In position 18 the circuit of down-drive magnet 335 is closed over the upper left contact of cam 316, upper right contact of cam 313, upper right contact of cam 317 to ground. The final selector is restored to normal under the control of down-drive magnet 335. When it reaches normal a circuit is closed from battery through the winding of sequence switch magnet 300, upper right contact of cam 321, normal commutator segment 336, brush 337, upper right contact of cam 317 to ground, advancing sequence switch 300 to normal. The incoming selector, the final selector and the test line are now all in normal condition.

When sequence switch 1000 arrives in position 18, register 1235 is held operated and closes a circuit from ground over its front contact, upper left and lower right contacts of cam 1003, left winding of relay 739 to

battery. Relay 739 operates and closes a circuit from battery over the upper left contact of cam 732, conductor 737, left winding of relay 955, brush 913 and its corresponding terminal, right front contact of relay 739, back contact of relay 740 to ground. Relay 955 operates and closes a circuit from ground over its inner left front contact, winding of relay 741 to battery. It also completes a circuit from battery through the winding of stepping magnet 917, outer left front contact of relay 955, conductor 953, lower right contact of cam 730 to ground. Magnet 917 operates in this circuit. Relay 955 locks through its right winding, right front contact, back contact of magnet 917 to the operating circuit of magnet 917 to insure the complete operation of the magnet. Relay 741 in operating locks over the normal contact of relay 742, inner left front contact of relay 741 to ground at the upper left contact of cam 730. It also closes a locking circuit for relay 739 extending through the left winding and inner front contact of that relay, innermost front contact of relay 741 to ground at the upper left contact of cam 730. In addition relay 741 closes a circuit from battery through the left winding of relay 729, outer left front contact of relay 749 to ground at the upper left contact of cam 730. Relay 729 in operating opens the circuit of relay 1220 and that relay releases disconnecting the test sequence switch from the incoming selector.

The operation of relay 729 closes a circuit from battery through the winding of sequence switch magnet 1000, upper right contact of cam 1022, left front contact of relay 729, outer left back contact of relay 735, upper right contact of cam 720 to ground, advancing sequence switch 1000 to position 1.

When sequence switch 1000 reaches position 1, a circuit is closed from battery through the winding of relay 711, right contact of cam 712, winding of relay 713, right back contact of relay 743, left contacts of cam 1037, outer right front contact of relay 741 to ground. Relay 713 closes a holding circuit for relays 711 and 713 which may be traced as previously described through the winding of relay 713, resistance 714, conductor 716, back contact of relay 1422, conductor 1424, upper left and lower right contacts of cam 712 to ground at the front contact of relay 713. Relay 711 in operating closes a circuit from battery over the upper right contact of cam 732, winding of relay 743, right front contact of relay 711 to ground at the lower left contact of cam 720. At the same time a circuit is closed from battery through the winding of up-drive magnet 107 of the district selector, conductor 672, lower contact of cam 673, lower contact of cam 719, inner left front contact of relay 711, inner right front contact of relay

743, left contacts of cam 1037, outer right front contact of relay 741 to ground, advancing the district selector.

The operation of relay 743 opened the energizing circuit of relays 711 and 713 but 70 the holding circuit remained closed. As commutator brush 117 passes the next conducting segment of strip 114, ground is connected to conductor 680 and thence, as previously traced, to the front contact of relay 711, holding relay 711 operated and deenergizing relay 713 which opens the holding circuit of these two relays. When brush 117 leaves the conducting segment, relay 711 releases, opening the circuit of the up-drive 75 magnet and bringing the district selector brush set to rest on the terminals of the next incoming selector.

Relay 743 is held energized over its inner left front contact to ground at the outer right front contact of relay 739 when relay 711 releases. With relay 711 released and relay 743 operated, a circuit is closed from battery through the winding of relay 740, right back contact of relay 744, contact of 80 interrupter 745, outer left front contact of relay 743, right back contact of relay 711, lower left contact of cam 720 to ground. Relay 740 operates when the interrupter closes its contact and opens the circuit of 85 relay 955, which relay releases in turn releasing magnet 917 which thereupon steps its brush set to their next terminals.

Relay 740 also closes a circuit through its winding and the winding of relay 744, right 90 front contact of relay 740 to ground as previously traced. When the interrupter 745 opens its contact, relay 744 is permitted to operate in this locking circuit of relay 740. With relay 744 operated the next closure of interrupter 745 completes a circuit from ground as previously traced over the contact of interrupter 745, front contact of relay 744, middle right front contact of relay 741, upper contact of key 731, winding of relay 742 to battery. Relay 742 in operating 95 opens the holding circuit of relay 741 and that relay releases, in turn releasing relay 739. The release of relay 739 opens the locking circuit of relay 743 which relay 100 opens the locking circuit of relay 740 and 744 so that these also release. The release of relay 741 opens the energizing circuit for relay 729, but the previously described circuit 105 through the right winding of that relay is closed to hold that relay energized provided the second incoming selector is busy.

If the incoming selector is idle relay 729 releases and relay 1220 is operated as previously described after which the second incoming selector will be tested in the manner described for the first incoming selector.

Check of locating selectors.

Outgoing trunks from the district or 120

office selector are arranged in groups of 10 with an intermediate trunk known as an overflow trunk between each group. These trunks are numbered consecutively from the bottom to the top, beginning with 0 and ending with 99. It therefore follows that the overflow trunks will bear the numbers 10, 21, 32, 43, 54, 65, 76, 87, 93 and 99, the last two groups containing only five trunks each. When a trunk group has been tested the operations described for advancing the district selector to the next incoming selector will result in the positioning of the district selector on an overflow terminal. One of the functions of the locating selectors of Figure 9 is to indicate the number of the incoming selector being tested should trouble arise and should it be necessary to readjust the apparatus. To that end, when the test of a group is begun, the locating selectors are positioned under the control of the directing selector on terminals corresponding to the position of the incoming selector to be tested on the test selector frame. The units locating selector is advanced one step at the same time the test selector is advanced.

Two sets of lamps 920 and 930 are lighted with sequence switch 700 in position 7 by the operation of key 956 to indicate the number of incoming selector under test on the district, or office, frame. This incoming selector is further identified by the set of lamps 940 which are lighted in accordance with the position of the connecting sequence switches of Figure 6, by the operation of key 956, and further by the lighting of one of the set of lamps 960 which are controlled by the directing selector.

Since the locating selector 900 controls the selection of the group of incoming selectors to be tested, there is little likelihood that the wrong group may be selected but since the advance of the district selector and the locating selector during tests within the group is controlled simultaneously, but independently, there is a possibility that the district selector may overthrow, thus skipping an incoming selector or that the district selector or the locating selector may get out of synchronism for some reason.

In some cases the group of trunks outgoing to a particular office may be very large and the overflow terminals will be made busy so that the district selector will pass by them in trunk hunting. When the district selector is being advanced by the test circuit it cannot pass the overflow terminal in the ordinary manner. However, a circuit is closed from ground over the right contact of cam 110, brush 111, commutator strip 108 which is provided with conducting segments at overflow positions, conductor 674, lower contact of cam 675, upper contacts of cam 706, winding of relay 735, to battery. Relay 735 operates and closes a circuit from

battery through the right winding of relay 739, brush 912 and its corresponding contact brush 902 and its corresponding contact, outer right front contact of relay 735, left back contact of either relay 745 or 746, right back contact of relay 740 to ground. The operation of relay 739 initiates the same cycle of operations which was previously described and causes the advance of the units locating selector and the district selector to the next incoming selector.

The units locating selector is moved over its No. 11 and 22 terminals, which are unused, and the tens locating selector is advanced as follows: When the units locating selector is moved to its No. 11 or 21 terminal, the operation of relay 739 closes a circuit from battery over conductor 737, right winding of relay 954, terminal 11 or 22 of brush 915, left contacts of cam 748, contact 610 of key 601 to ground. Relay 954 operates and closes a circuit from battery, winding of magnet 907 of the tens locating selector, outer right front contact of relay 954 to ground, advancing the switch 900 to its next terminal. The circuit for relay 955 over brush 913 is not completed with that brush engaging terminals 11 or 22. However, a circuit is closed from battery through the winding of magnet 917, back contact of magnet 917, right back contact of relay 955, inner right front contact of relay 954, terminal 11 or 22 of brush 915 to ground, as previously traced. The operation of magnet 917 in this circuit advances the units locating selector to its next terminals, opening the energizing circuit of relay 954 and the circuit of magnet 917. The release of relay 954 prior to the advance of the tens locating selector is prevented by means of a holding circuit through the left winding and left contact of relay 954, back contact of magnet 907 and ground at the outer right contact of relay 954.

110 *End of group.*

As many small groups of trunks may be tested as make up the large group outgoing to a particular office. When the last selector of such a large group has been tested, the district selector will be resting on an overflow trunk and relay 735 will be operated as previously described. Since the sleeve terminal is not made busy, relay 729 will be released. However, the test circuit is arranged to be reset before testing in another group. Therefore a circuit is provided from battery through the winding of relay 765, brush 901 and its corresponding terminal which is cross-connected to brush 802 of the directing selector to ground at the outer left front contact of relay 551. A circuit is also provided from battery through the winding of relay 746 and brush 911 to brush 802 and ground. With relays 765 and 746 operated a

circuit is closed from battery through the winding of sequence switch magnet 700, upper left contact of cam 747, left front contact of relay 746, inner right front contact of relay 735, front contact of relay 765, upper left contact of cam 725 to ground, advancing sequence switch 700 to position 8.

With sequence switch 700 in position 8 a circuit is closed from battery through the winding of down-drive magnet 118, conductor 691, lower contact of cam 692, lower left contact of cam 726 to ground. The district selector is restored under the control of down-drive magnet 118. With sequence switch 700 in position 8 a circuit is closed from battery through the winding of relay 1164, conductor 1165, lower right and upper left contacts of cam 748, contact 610 of key 601 to ground. The operation of relay 1164 closes a circuit from ground over its outer right front contact through the winding of relay 1161, inner left back contact of relay 116, inner left back contact of relay 1167 winding of magnet 806 to battery. It also closes the circuit from ground over its inner right front contact through the winding of relay 1162, inner right back contact of relay 1166, right back contact of relay 1167, winding of magnet 1107, outer left back contact of relay 1167, outer right back contact of relay 1166, left front contact of relay 1164 to battery. With relays 1161 and 1162 operated, when the district selector reaches normal, a circuit is closed from ground over the right contact of cam 110, brush 117, normal commutator segment 119, conductor 693, lower contact of cam 694, conductor 695, front contact of relay 1161, front contact of relay 1162, conductor 1163, upper left contact of cam 710, winding of sequence switch magnet 700 to battery, advancing sequence switch 700 to position 10.

Stepping magnets 807 and 1107 are energized in the circuits just traced for relays 1161 and 1162. When sequence switch 700 leaves position 8½ the circuit of relay 1164 is opened and that relay releases in turn releasing relays 1161 and 1162 and magnets 807 and 1107. The release of these magnets advances the directing selectors to their next terminals.

With the directing selectors in their next positions a new group of incoming selectors will be tested. This group may appear in a different part of the terminal bank of the same district selector; in the terminal bank of another district selector reached through the same connector sequence switch or in the terminal bank of a district selector reached through another connector sequence switch.

If the group appears on the same district selector the ground connected to the connector sequence switch by the directing selector will be ineffective and the district selections will proceed as previously described.

If the group appears in the terminal bank of the district selector reached when sequence switch 650 is in another position, 14 to 18 for example, ground will be connected from the directing selector to conductor 1168 and thence to the lower left contact of cam 653. This circuit advances sequence switch 650 to position 8. In position 8 ground is connected over the upper right contact of cam 652, lower right contact of cam 605, upper left contact of cam 653 to the winding of sequence switch magnet 650. The sequence switch advances to position 10 in this circuit. At this time the circuit through the directing selector is again closed and the sequence switch advances to position 14. In position 14, the above traced local circuit is closed and the sequence switch advances to position 16 which is the test position for the district selector to be used as a test selector at this time.

If the group to be tested had appeared in the terminal bank of a district selector reached through sequence switch 600, say in positions 14 to 18, ground will be connected through the directing selector to conductor 1169 and the upper left contact of cam 604. This circuit will advance sequence switch 600 from position 1 to position 2. With sequence switch 600 in position 2 a circuit is closed from ground over the left contact of cam 605, upper left contact of cam 653 to the winding of sequence switch magnet 650. Sequence switch 650 will be restored to one of its normal positions in this circuit. When sequence switch 650 reaches a normal position, ground is connected over the left contact of cam 605, lower left contact of cam 652, lower right contact of cam 604 to the winding of sequence switch magnet 600 advancing that sequence switch to position 7. In position 7 ground from the directing selector advances sequence switch 600 to position 8 and ground from cam 605 advances it to position 10. Ground from the directing selector advances sequence switch 600 to position 14 and ground from cam 605 advances it to position 16 which is the test position as above mentioned. The subsequent operations are the same as those previously described.

When all of the groups of incoming selectors associated with the first pair of directing selectors have been tested the directing selectors are advanced to their No. 21 terminals. With switch 800 on its No. 21 terminal a circuit is closed from ground over the outer left contact of relay 551, brush 802 and its No. 21 terminal, winding of relay 857 to battery. Relay 857 in operating closes a circuit from ground at its right front contact through the winding of relay 1167 to battery. A circuit is also closed from ground at the inner left front contact of relay 551, over the No. 21 terminal of

brush 1105, winding of relay 1150 to battery.

Relays 1167 and 1150 operate and transfer the operating circuits to the next directing selectors. The first directing selector re-

5 mains on its No. 21 terminal while the incoming selectors associated with the second directing selector are tested. As many directing selectors are provided as are necessary to test the entire number of incoming

10 selectors in the exchange. When the last incoming selector has been tested the last pair of directing selectors is advanced to the No. 21 terminal by cross-connection of the space terminals to the winding of relay 749, while

15 sequence switch 700 is restoring to normal. For simplicity in the disclosure only two pairs of the directing selectors have been shown. When the second pair of directing

20 selectors reaches its No. 21 terminal a circuit is closed from battery through lamp 1170, brush 1115, inner left front contact of relay 551 to ground. At the same time a

25 circuit is completed for relay 1151 in parallel with lamp 1170. Relay 1166 is also operated over the No. 21 terminal of brush 1114 to ground at the inner right front contact of relay 551. With directing selector

30 810 engaging its No. 21 terminals a circuit is closed from battery through the winding of relay 858, No. 21 terminal of brush 812 to ground at the outer left front contact of relay 551. Relay 858 opens the circuit for

35 restoring switch 1110 until switch 810 has been restored.

36 The directing selectors remain on the No. 21 terminals until the attendant responds to the lighting of lamp 1170. If another cycle of tests is not desired, key 601 is released and key 558 is operated.

40 The operation of key 558 closes a circuit from battery through the winding of relay 552, inner upper left operated contact of key 558, lower right operated contact of key 558 to ground. The operation of relay 552

45 closes a circuit from battery through the winding of relay 550, outer left front contact of relay 552 to ground.

46 Relay 550 in operating extends its operating ground over its inner left front contact to the winding of relay 551, operating that

50 relay. The restoration of key 601 permits the release of relay 1154 and in turn relays 1153 and 551.

55 Two circuits are now prepared, one from battery through the winding and back contact of magnet 817, winding of relay 1171, outer left front contact of relay 1166, inner right front contact of relay 550 to ground, and the second through the winding and

60 back contact of magnet 817, brush 811 and its No. 21 terminal, left front contact of relay 1151, outer left front contact of relay 550, conductor 559, winding of relay 749 to ground at the lower right contact of cam

65 720. Relay 749 operates but serves no special

purpose at this time. Magnet 807 operates in the circuit above described but the circuit through relay 749 prevents the operation of relay 1171.

The operation of magnet 817 advances 70 directing selector 810 to normal. When relay 810 leaves its No. 21 terminal, the circuit through relay 749 is opened permitting the operation of relay 1171.

The operation of relay 1171 closes battery 75 over the front contact of that relay to the winding of magnet 1117, from which the circuit is extended over the back contact of magnet 1117, brush 1111, back contact of relay 858 and thence over the energizing circuit 80 of magnet 817 to ground. Magnet 1117 operates and steps directing selector 1110 to normal.

As soon as selector 1110 leaves its No. 21 terminal the circuits of relays 1151 and 1166 85 are opened and these relays release. A circuit is thereupon closed from battery through the winding and back contact of magnet 807, No. 21 terminal of brush 801, outer left back contact of relay 1151, outer left front contact 90 of relay 550 to ground over conductor 559.

As in the case of magnet 807, a second circuit is prepared through the magnet and through the winding of relay 850, which is completed over the middle left front contact of relay 1167, outer left back contact 95 of relay 1166 to ground at the inner right front contact of relay 550. As before, this

circuit is ineffective until the first directing selector leaves the No. 21 terminal. When 100 this happens relay 850 operates to supply battery to the magnet of the second directing selector and that selector is then advanced to normal.

Test of a particular incoming selector.

If it should be desired to test a particular circuit or start the automatic test at some other point than the fixed starting point, key 556 may be operated. One of the set 110 of keys 510 will be operated and if the selector to be tested appears in a group connected to the second half of the directing selector terminal bank, key 500 will also be operated; if it appears in a group connected to the No. 20 terminal of a directing selector, key 501 and the zero key of the 510 group will be operated. One of the group of keys numbered 520 will be operated to select a particular directing selector to be employed

115 and one of the keys of the group 530 will be operated to select the group of incoming selectors in which the one to be tested appears. The operation of a corresponding pair of relays such as 1167 and 1150 or 1166

120 and 1151 will take place and the corresponding pair of directing selectors 800 and 1100 or 810 or 1110 will be moved off normal.

The operation of key 556 connects ground 125 to the keys of set 510 through which ground

130

is connected to the terminals of brushes 801 and 1101. The operation of one of the keys of set 510 removes ground from a particular terminal of brushes 801 and 1101 and prevents the advance of the directing selector from that point when it has been advanced thereto by ground over the other keys.

The operation of any one of the keys of set 520 transfers the ground supplied from brush 1103 to the locating selectors over the contact of the operated key to the terminal of the locating selector corresponding to said key. With all the keys set, start key 601 will be operated. Assuming that key 3 of set 510 and key 0 of set 520 have been operated, relay 701 will be operated and the two circuits for magnet 807 closed as described. When switch 800 moves to its No. 1 terminals ground will be connected there-
to over the lower right contact of key 720, winding of relay 749, conductor 559, outer right contact of key 556, and the right normal contact of the No. 1 key of set 510. Magnet 807 reoperates and steps switch 800 to its No. 2 terminals. Similar circuits are closed over the Nos. 2, 3, 4, 5, 6, 7 and 8 keys of set 510. The operation of the No. 9 key removes ground from the No. 9 terminal of brush 801 and switch 800 comes to rest in that position. The removal of ground permits relay 850 to operate in the second circuit of magnet 817, supplying battery to magnet 1107. Magnet 1107 steps switch 1100 to its No. 1 terminals in the usual manner.
The terminals of the cross-connecting racks 808 and 1108 are strapped together as well as to key set 510, hence ground is provided for reoperating magnet 1107 until switch 1100 also engages its No. 9 terminals. The district selector to be used as a test selector and the group including the incoming selector to be tested will be selected as previously described.

At the time that relay 729 is operated and then connected to the sleeve to test whether the incoming selector is busy, a circuit is closed from ground at the upper right contact of cam 736, over the left back contact of relay 735, conductor 750, outer left operated contact of key 556, conductor 557, right front contact of relay 729, contact 760 of key 731, key 751, right winding of relay 729 to battery at the lower right contact of cam 732. Relay 729 is held operated in this circuit. Either key 721 or 751 is then operated removing the shunt around the winding of relay 738 and permitting that relay to operate.

The operation of relay 738 closes a circuit from battery over the upper right contact of cam 732, winding of relay 752, front contact of relay 738, inner left back contact of relay 735 to ground at the upper right contact of cam 736. Relay 752 locks over its inner right front contact to ground at the

left back contact of relay 744. Relay 752 in operating connects ground to the right winding of relay 739, operating that relay.

The operation of relay 739 initiates the series of operations previously described to advance the district selector to its next terminals. The advance of the district selector causes the operation of relay 744 as previously described which opens the locking circuit of relay 752 and permits that relay to release. If key 751 has been employed to advance the district selector it must now be released in order to permit the operation of relay 742 and the completion of the cycle of operations.

If key 751 has been operated the cycle of operations will be automatically repeated until the key is restored to bring the district selector to rest on the desired incoming selector. It will be possible to determine the position of the district selector by operating key 956 so that the lamp sets 920 and 930 will be lighted. When the district selector is properly located, key 556 is released. The release of key 556 removes ground from the right winding of relay 729 and connects it to the sleeve brush of the test selector to determine whether or not the desired incoming selector is busy. Further tests will take place in the manner described.

Alarm switches.

For the purpose of informing the operator when the tests have not progressed properly two timing switches are provided 1200 and 1210. Timing switch 1210 is employed to measure the time during which the test selector and the incoming selector are busy, while switch 1200 is employed to measure off the reasonable operating period for the test operations. When the start key 601 is operated a circuit is closed from battery through the winding of relay 1216, normal contact of brush 1214, contact 1233 of key 1234, right back contact of relay 1220, contact 609 of key 601 to ground. Relay 1216 locks over its left front contact to this energizing circuit. It completes a circuit from battery through the winding of stepping magnet 1215, brush 1212, outer right front contact of relay 1216 through interrupter 1217 to ground. Switch 1210 is advanced under the control of interrupter 1217. When relay 1220 operates at the time that the incoming selector becomes idle, the locking circuit of relay 1216 is opened and that relay releases. It thereupon closes a circuit from battery through the winding of magnet 1215, back contact of magnet 1215, brush 1211 and its off-normal terminals, right back contact of relay 1216 to ground. This circuit advances switch 1210 to normal. If the switch reaches the position next before normal before relay 1220 operates a

circuit is closed from battery at the alarm circuit through lamp 1218, brush 1213, inner right front contact of relay 1216 to ground, causing an alarm to be sounded and lamp 5 1218 to light. The attendant may then determine the reason why the circuit has remained busy for an undue length of time. The operation of key 1234 will release relay 1216 and stop the alarm.

10 When relay 1220 operates a circuit is closed from battery through the winding of relay 1206, brush 1204 and its normal terminal, back contact of relay 1207, contact 1237 of key 1234, conductor 1238, lower right 15 contact of cam 1011, inner right front contact of relay 1220, contact 609 of key 601 to ground. Relay 1206 operates and locks over its left front contact to this operating circuit which is maintained in off-normal 20 positions of sequence switch 1000 by direct ground at the upper contact of cam 1011. The operation of relay 1206 closes a circuit from battery through the winding of stepping magnet 1205, brush 1202, outer right 25 front contact of relay 1206 to ground through interrupter 1217. Switch 1200 is advanced from position to position under the control of interrupter 1217.

When sequence switch 1000 reaches position 30 1 and relay 1220 is released in the manner described, the locking circuit of relay 1206 is opened and that relay released closing a circuit from battery through the winding and over the back contact of magnet 1205, brush 35 1201 and its off-normal terminals, right back contact of relay 1206 to ground, advancing switch 1200 to normal. If it reaches its pre-normal position before relay 1220 is released a circuit is closed from battery through the 40 winding of register 1239, brush 1203 and its pre-normal contact, inner right front contact of relay 1206 to ground. The operation of register 1239 closes a circuit from battery through the alarm circuit, lamp 45 1208 to ground at the contact of the register causing the sounding of the alarm and the lighting of the lamp 1208 to indicate that trouble has been encountered. The operation of key 1234 closes a circuit from battery 50 through the winding of relay 1207 to conductor 1238, and that relay locks to conductor 1238 over its right front contact thus preventing the starting of a new timing period until the circuits have reached 55 normal.

Manual advance following trouble.

Should the test sequence switch fail to 60 advance due to the failure of the district or incoming selectors to function properly, key 1038 will be operated closing a circuit from ground over the closed contact of the key, winding of relay 1240 to battery. The operation of relay 1240 closes a circuit for relay 65 1232 over its right front contact, conductor

1238 to ground over the upper left contact of cam 1011. Relay 1232 locks over its inner left front contact and upper left contact of cam 1018 to ground.

Relay 1240 in operating closes a circuit 70 from battery through the winding of sequence switch magnet 1000, lower right contact of cam 1012, outer left front contact of relay 1240, conductor 1238 to ground, advancing sequence switch 1000 to position 16. 75 When the sequence switch arrives in position 16, relay 1433 is operated as described in the normal operation of the circuit. The operation of relay 1433 in turn causes the operation of relay 1437. With sequence switch 1000 in position 16, relay 1240 also closes a circuit from battery through the winding of relay 1418, conductor 1441, Figures 14 and 12, inner left front contact of relay 1240, conductor 1448 to ground at the 80 left contact of cam 1035. Relay 1418 closes the usual locking circuit for itself through the windings of relays 1419 and 1420, but these relays do not operate since they are shunted by the energizing circuit of relay 1418. When key 1038 is released, relay 1240 85 will release and open the energizing circuit of relay 1418 to permit relays 1419 and 1420 to operate. The operation of relay 1419 90 closes a circuit from ground over its front contact, conductor 1024, left contacts of cam 1023, right back contact of relay 1313, interrupter 1310, lower contact of cam 1033, conductor 1442, Figures 10 and 14, back contact of relay 1401, winding of relay 1400 to battery. Relays 1400, 1401, 1402 and 1403 95 will be energized under the control of interrupter 1310. With relay 1403 operated the next closure of interrupter 1310 will 100 complete a circuit as previously traced to the armature of relay 1401, over the front contact of that relay, front contact of relay 1403, left back contact of relay 1440, outer right front contact of relay 1437, outer lower left normal contact of key 1302, outer right 105 front contact of relay 1232, winding of relay 1300 to battery. Relay 1300 in operating closes a circuit from battery through the winding of sequence switch magnet 1000, lower left contact of cam 1012, outer left 110 front contact of relay 1300, upper left contact of cam 1011 to ground, advancing sequence switch 1000 to position 17.

The sequence switch remains in position 115 17 until relay 1224 or relay 1228 operates due to the restoration of the incoming selector to normal in the manner previously described. Should the failure of the incoming selector be of such a nature that these relays do not operate, a second closure of key 1038 will cause the operation of relays 1240 and 1232 as before, relay 1232 again locking to the upper right contact of cam 1018.

When key 1038 is released, releasing relay 120

1240, a circuit is closed from battery through the winding of relay 1300, left contacts of cam 1034, inner right front contact of relay 1232, left back contact of relay 1240 to ground over conductor 1238. Relay 1300 locks over its inner left front contact to ground at the lower right contact of cam 1026.

10 The operation of relay 1300 operates registers 1036 and 1235 in turn, register 1235 advancing sequence switch 1000 to position 18 in the usual manner. The restoration of sequence switch 1000 is under the control of relay 729.

15 *Repeat tests.*

20 In case it is desired to repeat a test on a given selector, repeat key 1039 is operated, closing an obvious circuit for repeat relay 1004 which locks to ground at the lower right contact of cam 1018. The operation of relay 1004 transfers the operating circuit closed by register 1036 from register 1235 25 to register 1040. The operation of register 1040 moves the sequence switch 1000 from position 18 to position 1 where the cycle of operations will be repeated.

30 *Brush continuity.*

35 It is possible that for some reason the brushes of the incoming selector may make good contact at the test line and not make good contact in some other group of lines. In order to test the contact of the brushes key 1302 will be operated. The operation of key 1302 together with one of the keys of group 1050 and 1060 extends the counting relay circuit for controlling incoming brush 40 and incoming group selections to any desired set of counting relays so that any brush may be tested in any group. It also will transfer the lead controlling final brush selection so as to select the No. 1 final brush 45 and will open the leads controlling final tens and final units selections. The operation of the test circuit through final brush selection which takes place in position 6 of sequence switch 1000 is the same as previously described. Sequence switch 1000 will be advanced from position 8 directly to position 13 in a circuit over the upper left contact of cam 1022, inner upper left operated contact of key 1302, upper left contact of cam 50 1026 to ground.

55 In position 13 the usual test for relay 203 is made and sequence switch 1000 advanced to position 15. In position 15 the test of relay 205 is made but since the circuit controlled by the interrupter 1310 is directed to the No. 5 counting relay there is no time interval and the opening of interrupter 1310 causes the operation of relay 1300 and the advance of sequence switch 1000 to position 16.

While sequence switch 1000 is still in position 15 a circuit is closed from battery through the winding of relay 1418, conductor 1441, Figures 14 and 10, lower contact of cam 1029, upper right contact of cam 1016, conductor 1434, inner right back contact of relay 1433, front contact of relay 1309 which has been operated in the usual manner, conductor 1025 to ground at the back contact of relay 1419. The advance 75 of sequence switch 1000 from position 15 opens this energizing circuit but the usual locking circuit through the windings of relays 1419 and 1420 has been closed and these relays now operate.

80 The operation of relay 1419 supplies ground for operating relay 1400 under the control of interrupter 1310 in the manner previously described. However, the locking circuit for relays 1400 to 1403 is provided at the outer lower right operated contact of key 1302 at this time.

85 The operation of relay 1433 extends ground over its front contact, left back contact of relay 1440, outer right front contact of relay 1437, outer lower left operated contact of key 1302 to the winding of relay 1300. Relay 1300 advances sequence switch 1000 to position 17, in which position the fundamental circuit is opened.

90 From the previous description of a complete test it will be apparent that the operation of the incoming selector to select a final selector will advance sequence switch 200 to position 8. The brush selecting operation of the final selector will depend upon the brushes of the incoming selector making good contact with the terminal upon which they are resting and hence the completion of this operation will indicate to the test circuit that the brushes are making satisfactory contact. Following brush selection the final selector sequence switch 300 will be in position 3. Since no further selections are to be made sequence switch 300 does not advance from position 3. Sequence switches 200 and 300 remain in these positions until sequence switch 1000 is advanced to position 17.

95 With sequence switch 200 in position 8, a circuit is closed from battery through the right winding of relay 205, upper winding of coil 233, lower contact of interrupter 257, upper contact of cam 226 to ground when the interrupter contact closes. Relay 205 100 operates and closes a circuit from ground over the right contacts of cam 214, left winding of relay 205, lower winding of coil 233, left contacts of cam 243, right front contact of relay 205, left contacts of cam 238, winding of supervisory relay 240, lower right winding of repeating coil 241 to battery.

105 When interrupter 257 closes its upper contact a circuit is closed from ground over the upper contact of cam 226, upper contact 110

of interrupter 247, front contact of supervisory relay 240, left winding of relay 206, resistance 225 to battery. Relay 206 operates and closes a circuit from battery through the winding of sequence switch magnet 200, lower left contact of cam 216, left front contact of relay 206, upper left contact of cam 209 to ground, advancing sequence switch 200 to position 9. When the operate test of relay 203 is made, a circuit is closed from battery through the right winding of relay 206, upper left contact of cam 207, lower left contact of cam 208, front contact of relay 203, lower right contact of cam 209 to ground. Sequence switch 200 is advanced from position 9 to position 11 by relay 206.

With sequence switch 200 in position 11, relay 205 is connected to the trunk conductors 213 and 214 as previously described and the operation of the test circuit with sequence switch 1000 in position 16 causes the operation of relay 205. Relay 205 in turn closes a circuit for operating relay 206 and relay 206 recloses the circuit for advancing sequence switch 200, this time to position 12. Relay 205 remains operated and sequence switch 200 remains in position 12 until the fundamental circuit is opened by the advance of sequence switch 1000 to position 17. The release of relay 205 permits the operation of relay 203 and that relay on operating operates relay 206. Relay 206 advances sequence switch 200 out of positions 12, 13 and 14 into position 15. Sequence switch 200 is advanced to position 16 as previously described. Sequence switch 200 is then advanced to position 18 in a circuit over the upper right and lower left contacts of cam 208, front contact of cam 203, lower right contact of cam 209 to ground. In position 18 the down-drive magnet is energized as previously described and the sequence switch advanced to position 1.

Passing busy selectors.

If it is desired to pass all incoming selectors that are busy rather than to wait for them to become idle, key 751 will be operated. The operation of key 751 opens the shunt around relay 738 and therefore introduces it into the test circuit through the right winding of relay 729. When the test circuit encounters a busy incoming selector relay 738 will operate and will close a circuit from battery over the upper right contact of cam 732, winding of relay 752, front contact of relay 738, back contact of relay 735, upper right contact of cam 736 to ground. Relay 752 will cause the operation of the busy register 753. It will also close a circuit from battery through the right winding of relay 739 to ground at its outer right front contact and will close a locking

circuit for itself to ground at the back contact of relay 744. The operation of relay 739 will initiate the series of operations described in the regular test to advance the district selector to the next incoming selector. Relay 738 is released due to a shunt closed around its winding by relay 741 and relay 752 is released by the opening of its locking circuit due to the operation of relay 744. If the next incoming selector is also busy, when relay 741 releases the test circuit through the right winding of relay 729 is again extended through the winding of relay 738 and the cycle of operations repeated until an idle incoming selector is reached.

If in the course of a routine test a busy incoming selector is encountered and it is desired to pass on to the next one, key 731 may be operated. The operation is essentially the same as that when key 751 is operated except that as long as key 731 remains operated no circuit is closed for relay 742 and the test cannot progress until the key is restored.

Rapid test to busy line.

Some times it is desirable to make a rapid test of the incoming selectors and for this purpose the selectors are successively directed to a busy line instead of to the test line. For this purpose key 1304 is operated, which transfers the counting relay circuits from those used in selecting the test line to those which will direct the incoming and final selectors to a line which is made busy for that purpose. The test circuit will function the same as for an automatic test until it reaches position 15. In position 15 the fundamental circuit will be opened.

A circuit will be supplied for relay 1312 over the left back contact of relay 1225, inner upper left operated contact of key 1304 to ground at the upper right contact of cam 1026. A circuit is also provided for relay 1300 extending over the left contacts of cam 1028, inner left back contact of relay 1313 to the circuit just traced for relay 1312. These relays operate and move sequence switch 1000 to position 16. In position 16 the previously traced fundamental circuit is closed through relay 1309 which relay operates and in turn operates relay 1447 as before.

When a final selector encounters a busy line battery reversal will be sent out over the trunk circuit in the manner to be described and relay 1309 will operate in response to these reversals.

With sequence switch 1000 in position 16, relay 1433 is operated in the usual manner and, since key 1304 is operated, a circuit is closed from battery through the winding of relay 1440, inner lower left operated contact of key 1304, next to the outer front contact of relay 1433 to ground.

With relay 1440 operated, the first operation of relay 1309 closes a circuit from battery through the winding of relay 1412, back contact of relay 1413, conductor 1435, 5 outer right front contact of relay 1440, right front contact of relay 1447, right back contact of relay 1446, next to the inner front contact of relay 1433, conductor 1431, front contact of relay 1309, conductor 1025 to 10 ground. The first release of relay 1309 operates relay 1413 and subsequently relays 1414 to 1420 are operated under the control of relay 1309.

The operation of relay 1419 closes a circuit 15 from ground at its front contact, conductor 1024, left contacts of cam 1023, right back contact of relay 1313, interrupter 1310, lower contact of cam 1033, conductor 1442, Figures 10 and 14, back contact of relay 1401, 20 winding of relay 1400 to battery.

Relays 1400 to 1403 are operated under the control of interrupter 1310, the locking circuit for these relays extending over the outer front contact of relay 1433 to ground 25 at the middle left front contact of relay 1440. With relay 1403 operated the next closure of interrupter 1310 closes a circuit from battery through the winding of relay 1300, inner left front contact of relay 1440, 30 front contact of relay 1403, front contact of relay 1401, conductor 1442, Figures 14 and 10 and thence as traced to ground at the front contact of relay 1419. Relay 1300 advances the sequence switch to position 17 in 35 which position it will remain until the incoming selector has returned to normal.

It will be remembered that when the final selector was leaving position 10, relay 306 was connected through both windings to 40 sleeve brush 323 as a test for busy condition. If the line is busy, relay 306 remains operated when sequence switch 300 reaches position 11 and locks through its two windings, upper right and lower left contacts 45 of cam 308 to ground at the right front contact of relay 306. With relay 306 operated in position 12, down-drive magnet 335 is operated over the upper left contact of cam 316, lower right contact of cam 313 to 50 ground at the right front contact of relay 306. The final selector is restored to normal under the control of down-drive magnet 335.

With sequence switch 300 in position 12, a circuit is closed for relay 312, over the upper right and lower left contacts of cam 327, 55 normal commutator segment 336, brush 337, upper right contact of cam 317 to ground. Relay 312 in operating closes a circuit from battery through the winding of sequence switch magnet 300, lower right and upper left contacts of cam 314, right front contact of relay 312 to ground, advancing sequence switch 300 to position 13. Sequence switch 300 is then advanced to position 14 in a cir-

cuit over the upper right contact of cam 65 221, normal commutator segment 336, brush 337, upper right contact of cam 317 to ground. When sequence switch 300 leaves position 12 the locking circuit of relay 306 is opened and that relay releases. When sequence switch 300 reaches position 14, ground over interrupter 338 completes a circuit over the upper left contact of cam 326 to the left winding of relay 306 operating that relay. Relay 306 in operating 75 closes a circuit from ground through the secondary winding of tone coil 339, upper contact of cam 305, resistance 304, upper left and lower right contacts of cam 308, left front contact of relay 306, left contacts of cam 309 to ring conductor 304 whence this circuit may be further traced over brush 223, upper left and lower right contacts of cam 232, upper left contact of cam 201, lower right contact of cam 202, winding of relay 203 to battery. Each time that relay 306 operates, relay 1309 of the test circuit is released performing the functions above described. The further release of the incoming selector and final selector is the same as 90 previously described.

Temporary stop of test.

If at any time it is desired to stop the test for any purpose such as luncheon period, etc., key 601 will be released. The release of key 601 prevents the advance of sequence switch 700 from position 1. It does provide a ground for moving sequence switch 700 from position 7 when sequence switch 1000 reaches position 1. This circuit may be traced from battery through the winding of magnet 700, upper right contact of cam 747, lower left and upper right contacts of cam 1003, contact 611 of key 601 to ground. With the sequence switch 700 in position 8, the district selector used as the test selector is restored to normal in the manner described.

In positions 9+11 of sequence switch 700, sequence switch 650 will be restored to normal in a circuit over the upper left contact of cam 653, lower contacts of cam 715 to ground at contact 612 of key 601. With sequence switch 650 normal, a circuit is closed from battery through the winding of sequence switch magnet 600, lower right contact of cam 604, lower left contact of cam 652, lower contacts of cam 715 to ground at contact 612 of key 601. The directing selector will not be advanced. At the completion of the stopped period the re-operation of key 601 will operate relay 701, and permit the advance of sequence switch 700 from position 1. The test will be resumed at the beginning of the group of lines in which the last incoming selector tested appeared.

Return to normal.

If it is desired to return the test circuit to normal from some point other than the end of the cycle, key 558 will be operated in turn operating relays 551, 550 and 552. Relay 552 locks over its inner right front contact to the lower contact of cam 736 as well as sequence switch 700 is off-normal and through the front contact of relay 749 to ground at the lower right contact of cam 720 while the directing selectors are returning to normal, since relay 749 is operated in the circuit of the stepping magnets. The operation of relay 550 opens the circuit for advancing the directing selectors from normal. The operation of key 558 closes ground for moving sequence switch 700 from position 7 when sequence switch 1000 reaches position 1, following the completion of a test. With sequence switch 700 in position 8 the directing selectors which have been in use will be advanced one terminal and relays 1164, 1162 and 1161 operated. The operation of these relays advances sequence switch 700 to position 9 in which position ground from the lower right contact of cam 720 will be connected through keys 510 to terminals 1 to 20 of brushes 801, 811, 1101 and 1111. The directing selectors will thus be advanced to their No. 21 terminal. They will then be advanced to normal after which all earlier directing selectors are restored to normal in turn. With sequence switch 35 700 in position 9 the connector sequence switch which has been in use is also restored to normal.

Second end of cycle.

In large offices it is possible that two test circuits may be installed. The second test circuit will then be started on its circuit from some point near the middle of the incoming selectors. To avoid both test circuits testing over the same groups, an intermediate end of cycle point is established. In this case lamp 1170 will be connected not only to the last terminal of the last directing selector but will by means of the cross-connecting rack be connected to some intermediate point. The point corresponding to this one is opened on all directing selector arcs except the arc served by brush 1105 or 1115 which serves to operate relay 55 1151. The corresponding point on the arc served by brush 1101 or 1111 is grounded over the front contact of relay 1151 to provide means for restoring the directing selector to normal.

Since the corresponding point on other arcs is opened the test circuit will stop at this point and a new test on the second half must be started by means of the key set 510.

What is claimed is:

1. In a testing system, groups of appa-

ratus to be tested, a progressively operable register, means to position said register, means to select a group of apparatus in accordance with the setting of said register, means for successively testing each apparatus in the selected group, means to indicate the identity of the apparatus under test and means operated following the test of a predetermined number of said apparatus to test the accuracy of said indication. 70 75

2. In a testing system, groups of apparatus to be tested, a progressively operable register, means to position said register, means to select a group of apparatus in accordance with the setting of said register, 80 means for successively testing each apparatus in the selected group, means to indicate the identity of the apparatus under test, means operated following the test of a predetermined number of said apparatus to test 85 the accuracy of said indication, and means to prevent the testing of additional apparatus if said indication is not correct.

3. In a testing system, automatic switches to be tested, a plurality of test selectors each having access to certain ones of said switches, a registering device, means to position said registering device, means to select a test selector in accordance with the setting of said registering device, means to operate said test selector to seize an automatic switch, means to test said automatic switch, and means for indicating the identity of said switch. 90 95

4. In a system for testing automatic switches, a test selector, means for controlling said test selector to select a switch to be tested comprising progressively operable means, means operated following the test of each switch to advance said test selector and said progressively operable means in synchronism, and means operated following the test of a predetermined number of switches to test whether said test selector and said progressively operable means are in synchronism. 100 105 110

5. In a system for testing automatic switches, a test selector, means for controlling said test selector to select a switch to be tested comprising progressively operable means, means operated following the test of each switch to advance said test selector and said progressively operable means in synchronism, and means under the control of said progressively operable means for indicating the position of said test selector. 115 120

6. In a system for testing automatic switches, a test selector, means for controlling said test selector to select a switch to be tested comprising progressively operable means, means operated following the test of each switch to advance said test selector and said progressively operable means in synchronism, means under the control of said progressively operable means for indicating 125 130 135

the position of said test selector, and means operated following the test of a predetermined number of switches to test the accuracy of said indication.

5 7. In a system for testing automatic switches, a test selector, means for controlling said test selector to select a switch to be tested comprising progressively operable means, means operated following the test of 10 each switch to advance said test selector and said progressively operable means in synchronism, means under the control of said progressively operable means for indicating the position of said test selector, and means 15 to prevent the test of additional switches if said indication is incorrect.

8. In a system for testing automatic switches, a test selector, means for controlling said test selector to select a switch to be tested comprising progressively operable means, means operated following the test of 20 each switch to advance said test selector and said progressively operable means in synchronism, means operated following the test 25 of a predetermined number of switches to test whether said test selector and said progressively operable means are in synchronism, and means to prevent the testing of additional switches if said test selector and said 30 progressively operable means are not in synchronism.

9. In a system for testing automatic switches divided into groups and sub-groups, means for controlling the selection of a 35 group of said switches for test, progressively operable means to control the selection of the first switch in a sub-group of said group, means operated following the test of each switch to control the selection of the next 40 switch and to advance said progressively operable means, and means under the control of said first mentioned means and said progressively operable means for indicating the 45 identity of the switch under test.

45 10. In a system for testing automatic switches arranged in groups and sub-groups, means for controlling the selection of a group of switches to be tested, progressively operable means to control the selection of the first switch in a sub-group of 50 said group, means operated following the test of each switch to control the selection of the next switch of the sub-group and to advance said progressively operable means, means under control of said first mentioned 55 means and said progressively operable means for indicating the identity of the switch under test, and means operated following the test of a predetermined number of said 60 switches to test the accuracy of said indication.

11. In a system for testing automatic switches arranged in groups and sub-groups, means for controlling the selection 65 of a group of switches to be tested, progres-

sively operable means to control the selection of the first switch in a sub-group of said group, means operated following the test of each switch to control the selection of the next switch of the sub-group and to advance 70 said progressively operable means, means under control of said first mentioned means and said progressively operable means for indicating the identity of the switch under test, and means operated following the test 75 of a predetermined number of said switches to prevent the testing of additional switches if said indication is not correct.

12. In a system for testing automatic switches arranged in groups and sub-groups, a test selector, means for controlling said test selector to select a group of said switches, progressively operable means to control said test selector to select the first switch in a sub-group of said group, means operated following the test of each switch to advance said test selector and said progressively operable means in synchronism, and means operated following the test of a predetermined number of said switches to test whether said test selector and said 90 progressively operable means are in synchronism.

13. In a system for testing automatic switches arranged in groups and sub-groups, a test selector, means for controlling said test selector to select a group of said switches, progressively operable means to control said test selector to select the first switch in a sub-group of said group, means operated following the test of each switch to advance said test selector and said progressively operable means in synchronism and means operated following the test of a predetermined number of said switches to prevent the testing of additional switches if 100 said test selector and said progressively operable means are not in synchronism.

14. In a system for testing automatic switches arranged in groups and sub-groups, a test selector, means for controlling said test selector to select a group of said switches, progressively operable means to control said test selector to select the first switch in a sub-group of said group, means operated following the test of each switch to advance said test selector and said progressively operable means in synchronism, and means operated following the test of the last switch 110 in a sub-group for testing whether said test selector and said progressively operable means are in synchronism.

15. In a system for testing automatic switches arranged in groups and sub-groups, a test selector, means for controlling said test selector to select a group of said switches, progressively operable means to control said test selector to select the first switch in a sub-group of said group, means operated following the test of each switch to advance 120

said test selector and said progressively operable means in synchronism, and means operated following the test of the last switch in a sub-group to prevent the testing of the 5 next sub-group of switches if said test selector and said progressively operable means are not in synchronism.

16. In a switching system, a pair of switches, stepping magnets therefor, two circuits through the stepping magnet of one of said switches, one of said circuits including a terminal of said switch, and the second of said circuits including a relay, means for completing said circuits to advance the 15 switch and open the first of said circuits to operate said relay, and means under the control of said relay for completing the circuit of the stepping magnet of said second switch.

20. 17. In a testing system a plurality of connector switches, each connector switch having a plurality of normal positions each followed by a group of operative positions, a registering device, and means under the control 25 of said registering device for moving any connector switch from any normal position to any group of operative positions.

18. In a testing system a plurality of connector switches, each connector switch having a plurality of normal positions each followed by a group of operative positions, a registering device, means under the control 30

of said registering device for moving any connector switch from any normal position to any group of operative positions, and for 35 restoring all other connecting switches to a normal position.

19. In a system for testing groups of apparatus, a plurality of connector switches, each connector switch having a plurality of 40 normal positions, each followed by a group of operative positions, a test selector associated with each group of operative positions, a progressively operable register, means to position said register, and means 45 under the control of said register to select said test selectors for use in non-sequential order.

20. In a system for testing groups of apparatus, a plurality of connector switches, each connector switch having a plurality of 50 normal positions, each followed by a group of operative positions, a test selector associated with each group of operative positions, a progressively operable register, 55 means to position said register, and means under the control of said register to successively position any connector switch in any group of operative positions to render the corresponding test selector operative. 60

In witness whereof, I hereunto subscribe my name this 10th day of March, A. D., 1926.

GEORGE R. MARTIN.
